COIN CHANGERS

Fred J. Melvin, Bellefontaine Neighbors, and Merrill P. Haversick, Normandy, Mo., assignors, by mesne assignments, to National Rejectors, Inc., a corporation of Missouri

Filed Oct. 15, 1958, Ser. No. 767,381
20 Claims. (Cl. 194—10)

This invention relates to improvements in coin changers. More particularly, this invention relates to improvements in coin changers which can accept coinage and send an impulse to a vending machine, and which can return change if the coinage has a value in excess of the sales price.

It is therefore an object of the present invention to provide an improved coin changer which can accept coinage and send an impulse to a vending machine, and which can return change if the coinage has a value in excess of the sales price.

This invention is an improvement on the invention shown and described in our co-pending application Serial Number 620,281 which was filed November 5, 1956 and which was granted March 26, 1963 as Letters Patent No. 3,082,852.

In the operation of the coin changer in said co-pending application, the inserted coins engage the actuator of the motor-controlling switch and hold that actuator in motor-energizing position throughout the first part of the cycle of operation of that coin-operated device. This means that there must be a closely-held dimensional and positional relationship between the coin passageways, the path of movement of the switch actuator, and the coin-responsive elements of the coin changer. In the coin-operated device of the present invention, a magnet is provided which holds the actuator of the motor-controlling switch in motor-energizing position during the first part of the cycle of operation of the coin changer and thereby obviates the need for a closely-held relationship between the coin passageways, the path of movement of the switch actuator, and the coin-responsive elements.

The magnet which holds the actuator of the motor-controlling switch is mounted on a lever which has an abutment; and that abutment is spaced from the magnet. Further, that abutment cooperates with the magnet to confine that switch actuator between them. The spacing between that magnet and that abutment is such that inserted coins can move the switch actuator from motor de-energizing position to motor-energizing position without requiring any movement of the lever on which that magnet and that abutment are mounted. Further, the spacing between that magnet and that abutment is such that the lever can subsequently move downwardly and place the abutment in position to hold the switch actuator in motor-energizing position. That lever can remain in lowered position and enable that abutment to hold the switch actuator in motor-energizing position until the end of the cycle of operation of the coin-operated device. As a result, the lever and its abutment and magnet can hold the switch actuator in motor-energizing position throughout an entire cycle of operation; and they do not require inserted coins to do more than move the switch actuator to motor-energizing position.

The coin changer provided by the present invention is a change-making device which utilizes a payout slide with a thickness somewhat less than the thickness of a nickel. Where the sales price of the article to be vended is five cents, and a quarter is inserted, that payout slide will be reciprocated four times to pay out four nickels as change; and where the sales price of the article to be vended is five cents, and a dime is inserted, that payout slide will

2

be reciprocated once to pay out one nickel as change. Where the sales price of the article to be vended is ten cents, and a quarter is inserted, it is only necessary to return three nickels as change; and where the sales price of the article to be vended is ten cents, and a dime is inserted, no nickels should be paid out as change. The present invention provides a change-making device that can, with an exceedingly simple adjustment, be set for a five cent or a ten cent sales price. The present invention does this by providing a cam with one of the lobes thereof movable relative to the rest of the lobes, and by using screws to secure that lobe to the cam.

In the manufacture of the change-making device of the present invention, it is desirable to form a large number of the relatively movable parts with punch presses. In the forming of parts with punch presses, burrs on the parts are unavoidable. Heretofore, those burrs have had to be removed by holding each relatively movable part adjacent a sanding belt or an abrasive wheel; and this involves extra handling of those parts and thereby increases the cost of the change-making device. The present invention obviates all need of sanding or grinding the parts, and of the resulting extra handling of those parts, by providing those relatively movable parts with ribs that permit those parts to move freely relative to each other despite the presence of the burrs.

The present invention has two coin-responsive elements that intercept, and that subsequently hold and feel, inserted coins; and those coin-responsive elements determine when and how many nickels are paid out as change. To enable those coin-responsive elements, and other elements of the change-making device to be made inexpensively by mass production methods, the present invention provides a gauging lever that precisely fixes the coin-holding positions of those coin-responsive elements. In doing so, that gauging lever avoids premature and accidental freeing of the coins from the coin-responsive elements.

That gauging lever has two abutments that are spaced apart both horizontally and vertically, and those abutments can be moved into and out of register with an abutting surface on one of the coin-responsive elements. When one of those abutments is in register with that abutting surface on that coin-responsive element, the coin-responsive elements can be moved a predetermined distance away from coin-feeling position; and when the other of those abutments is in register with that abutting surface on that coin-responsive element, the coin-responsive elements can be moved a second and greater predetermined distance away from coin-feeling position. When both of those abutments are out of register with that abutting surface on that coin-responsive element, the coin-responsive elements can be moved still further away from coin-feeling position.

The payout slide of the present invention is biased to coin-discharging position by springs, and it is moved away from coin-discharging position by the lobes of the cam. The springs, which bias the payout slide toward coin-discharging position, urge that slide against the lobes of the cam and thereby bias that cam for rotation in a direction opposite to its normal direction of rotation. Such opposite rotation could permit the payout slide to move to coin-discharging position and pay out an extra coin; and hence, such opposite rotation of the cam would be very objectionable and must be limited. The present invention limits such opposite rotation of the cam by providing that cam with a number of notches or abutments and by providing a latch that is engageable with those notches or abutments to limit opposite rotation of the cam. That latch and those notches or abutments permit unlimited rotation of the cam in its normal and desired di-

rection, but closely limit rotation of that cam in the opposite direction.

Other and further objects and advantages of the present invention should become apparent from an examination of the drawing and accompanying description.

In the drawing and accompanying description, a preferred embodiment of the present invention is shown and described but it is to be understood that the drawing and accompanying description are for the purpose of illustration only and do not limit the invention and that the invention will be defined by the appended claims.

In the drawing,

FIG. 1 is a partially broken, front elevational view of one embodiment of change-making device that is made in accordance with the principles and teachings of the present invention,

FIG. 2 is a partially broken, elevational view of the right-hand side of the change-making device of FIG. 1,

FIG. 3 is a vertical section through the change-making device of FIG. 1, and it is taken along the plane indicated by the line 3—3 in FIG. 1,

FIG. 4 is a plan view of a supporting plate used in the change-making device of FIG. 1,

FIG. 5 is a plan view of the payout slide of the change-making device of FIG. 1,

FIG. 6 is a plan view of the bottom wall of the change-making device of FIG. 1,

FIG. 7 is a sectional plan view through the change-making device of FIG. 1, and it is taken along the plane indicated by the line 7—7 in FIG. 1,

FIG. 8 is a sectional elevational view through a portion of the payout slide of FIG. 5, and it is taken along the plane indicated by the line 8—8 in FIG. 5,

FIG. 9 is another sectional view through the payout slide of FIG. 5, and it is taken along the plane indicated by the line 9—9 in FIG. 5,

FIG. 10 is yet another sectional elevational view through the payout slide of FIG. 5, and it is taken along the plane indicated by the line 10—10 in FIG. 5,

FIG. 11 is still another sectional elevational view through the payout slide of FIG. 5, and it is taken along the plane indicated by the line 11—11 in FIG. 5,

FIG. 12 is an additional sectional elevational view through the payout slide of FIG. 5, and it is taken along the plane indicated by the line 12—12 in FIG. 5,

FIG. 13 is a partially broken sectional elevational view of the change-making device of FIG. 1, and it is taken along the broken plane indicated by the line 13—13 in FIG. 1,

FIG. 14 is a rear elevational view of one rotatable lever that is used in the change-making device of FIG. 1,

FIG. 15 is an end elevational view of the rotatable lever of FIG. 14, and it is taken at the left-hand end of that lever,

FIG. 16 is a front elevational view of another rotatable lever that is used in the change-making device of FIG. 1,

FIG. 17 is a bottom view of the rotatable lever of FIG. 16,

FIG. 18 is a perspective view of one of the coin-responsive elements of the change-making device of FIG. 1, and it also shows some of the components that rotate that element,

FIG. 19 is a perspective view of the other coin-responsive element,

FIG. 20 is a partially-sectioned view of the multi-lobe section of the cam of the device of FIG. 1, and it is taken along the plane indicated by the line 20—20 in FIG. 13,

FIG. 21 is a partially-sectioned view of the notched section of the cam, and it is taken along the plane indicated by the line 21—21 in FIG. 13,

FIG. 22 is a partially-sectioned view showing the rear section of the cam, and it shows the lever and roller moved by that section of the cam, and it is taken along the plane indicated by the line 22—22 in FIG. 13,

FIG. 23 is a sectional view of a portion of the device

of FIG. 1, and it is taken along the plane indicated by the line 23—23 in FIG. 3,

FIG. 24 is a sectional view of another portion of the device of FIG. 1, and it is taken along the broken plane indicated by the line 24—24 in FIG. 3, and

FIG. 25 is another sectional view of the device of FIG. 1, and it is taken along the broken plane indicated by the line 24—24 in FIG. 3; but it shows the cam of that device after that cam has advanced almost a quarter of a revolution beyond the position shown in FIG. 24.

Referring to the drawing in detail, the numeral 30 generally denotes the frame used in one embodiment of change-making device that is made in accordance with the principles and teachings of the present invention. That frame is substantially identical with the frame of the change-making shown and described in said co-pending application; and it has the same slug rejector, the same notches to receive that slug rejector, and the same catches to hold that slug rejector.

The frame 30 has a central vertical wall 32, as shown by FIG. 3. A horizontal wall 34 is contiguous with, and extends rearwardly from, the top of the vertical wall 32; and a rear wall 36 extends vertically upwardly from the horizontal wall 34, as shown by FIG. 3. A vertical flange 38 is contiguous with the right-hand edges of the walls 32, 34 and 36, and a vertical flange 40 is contiguous with the left-hand edges of those walls. The vertical flange 38 differs from the corresponding vertical flange in said co-pending application in having a circular opening

39, rather than a keyhole-shaped opening, adjacent the bottom thereof. That keyhole-shaped opening is not necessary because of the adjustment feature made possible by that keyhole-shaped opening not being needed in the change-making device of the present invention. The vertical flange 40 of the frame 30 is substantially identical to the corresponding vertical flange in said co-pending application.

The wall 32 has a boss 31 on the upper right-hand portion of the front face thereof and that boss is shown by dotted lines in FIG. 23. That wall has three additional bosses on the upper right-hand portion of the front face thereof, and those bosses are denoted by the numerals 33, 35 and 37 in FIG. 23. The bosses 31 and 37 differ slightly from the corresponding bosses in said co-pending application. The bosses 31, 33, 35 and 37 guide a quarter as it moves downwardly from the slug rejector and passes along the front face of the wall 32. That quarter passes by two slots, not shown, in the wall 32 which are identical to the two slots shown by FIG. 23.

An accepted coin chute 42 is provided below the level of the said two slots, and that coin chute has a downwardly and rearwardly inclined wall, as shown by FIG. 3. That coin chute is preferably formed integrally with the wall 32, and it has a rearwardly disposed vertical wall portion. A horizontal stud 44 projects forwardly from the upper part of the front face of the inclined wall of the coin chute 42, and that stud is drilled and tapped. A boss 46 extends forwardly from the lower portion of the front face of the inclined wall of the coin chute 42, and that boss is contiguous and integral with the right-hand flange 38 of frame 30. A drilled and tapped opening is provided in the upper part of that boss to receive a screw. A generally L-shaped boss 48 extends forwardly from the lower portion of the front face of the inclined wall of the coin chute 42, and that boss is at the same level as the boss 46. The boss 48 also is drilled and tapped to receive a screw. A boss 49 is disposed below the level of the bosses 46 and 48, and that boss extends forwardly from the lower portion of the front face of the wall 32. That boss has a horizontal groove 50 therein, as shown by FIG. 3.

The numeral 52 denotes a pivot which is secured to the wall 32 of frame 30 at a point directly above the L-shaped boss 48, and that pivot extends forwardly from that wall. A stud 58 is provided on the front face of

wall 32, above the level of pivot 52 and to the left of boss 37 in FIG. 23, and that stud projects forwardly from that wall. An opening 60 is provided in the wall 32 intermediate the stud 58 and the boss 37, and that opening is rectangular with its long axis vertical. A pivot 62 is secured to, and projects forwardly from, the upper portion of the front face of wall 32, and that pivot is disposed to the left of the stud 58. An opening 64 is provided in the wall 32 intermediate the pivot 52 and the opening 60. A stud 66 is provided on the front face of wall 32, above and to the left of the opening 64, and that stud extends forwardly from that wall. A plate 68 is disposed forwardly of the front face of the wall 32, and that plate is adjacent an opening 70 in that wall; and plate 68 and opening 70 are directly below the stud 58. Openings 72 and 74 are provided in the wall 32 below, and to the left of, the pivot 52; and those openings are drilled and tapped. An arcuate opening 76 is provided in the wall 32 above, and to the left of, the stud 58; and that opening starts at a point above the pivot 62 and extends to the right. A generally rectangular opening 78 is provided in the wall 32 below the level of the pivot 62. The wall 32 also is provided with a forwardly offset portion 79, and that portion has a generally rectangular opening 82 in it. That opening has the sides thereof inclined to the vertical, as shown by FIG. 25. Also, the forwardly offset portion 79 has an opening 80 therethrough immediately above the opening 82.

A stud 81 extends forwardly from the front face of the wall 32, and that stud is immediately adjacent the left-hand edge of the opening 78. An opening 84 is provided in the upper portion of the wall 32, as shown by FIG. 1, and that opening is in register with the arcuate opening 76. The numeral 86 denotes a notch that is generally L-shaped in front elevation and that notch extends upwardly from the lower edge of the wall 32, as shown by FIG. 25.

A pivot 88 is secured to, and extends forwardly from, the forwardly offset portion 79 of wall 32, and that pivot is below, and to the right of, the opening 80 in that forwardly offset portion. The numeral 90 denotes an electric motor which has a gear housing 92 associated with it; and an output shaft 94 extends forwardly from that gear housing. The gear housing 92 is suitably secured to the forwardly offset portion 79 of the wall 32 by screws 95. A switch 96 is mounted at the rear face of the wall 32, as shown by FIG. 13; and that switch is immediately adjacent the left-hand edge of the opening 60. A pair of studs 98 are provided on the rear face of wall 32, and those studs are drilled and tapped to receive screws 100. Those screws fixedly secure the switch 96 to the studs 98 and thereby secure that switch to the wall 32. The switch arm 102 of switch 96 has a forwardly bent coin-receiving portion that extends through the arcuate slot, not shown, in wall 32 which is behind the lower slot of FIG. 23.

The numeral 104 denotes studs which are disposed above the level of the studs 98 and which extend rearwardly from the wall 32. Those studs are drilled and tapped, and screws 108 extend through openings in a switch 106 and seat in those studs. The switch arm 110 of switch 106 has a forwardly bent coin-receiving portion that extends through the arcuate slot, not shown, in wall 32 which is behind the upper slot of FIG. 23.

The numeral 112 denotes a stud which extends rearwardly from the upper portion of the wall 32, as shown by FIG. 3; and the rear portion of that stud is drilled and tapped to receive a screw 115. That stud 112 coacts with two other studs, not shown, which are adjacent the lower portions of the frame 30 to hold screws that secure rear cover plate 113 in position. One of those studs is adjacent the lower edge of a vertical wall 114 which is shown in FIG. 3, and which starts at a point above the top of the coin chute 42 and extends down below the bottom of that chute. That wall helps guide accepted

coins in their downward movement through the coin chute 42.

The numeral 116 denotes a switch, which is partially shown in FIGS. 24 and 25; and that switch is located at the rear face of wall 32. A bracket, not shown, is secured to that switch; and screws extend through that bracket and seat in the openings 72 and 74 in wall 32. Those screws maintain the switch 116 fixed relative to that wall, and they dispose the feeler 118 of that switch in register with the L-shaped notch 86 at the bottom of wall 32.

The numeral 120 denotes a switch that is mounted in front of the lower portion of coin chute 42, and that switch has ears with openings through which screws 123 extend to seat in the drilled and tapped openings in the bosses 46 and 48. The switch 120 has a slide button 122 that can be shifted to the right to close the contacts of that switch and which can be shifted to the position shown by FIG. 1 to open those contacts. A piece of insulation 124, such as fish paper, is mounted adjacent the switch 120; and that piece of insulation effectively protects the terminals and external leads of that switch from injury, from grounding and from shorting. A latch 126 is rotatably mounted on a screw 128 which is seated in the drilled and tapped opening in the boss 44, as shown by FIG. 1.

The numeral 130 denotes an L-shaped bracket that has a horizontal rib thereon, and that rib extends into the slot 50 in the boss 49. A screw 132 extends through an opening, not shown, in the bracket 130 and seats in a drilled and tapped opening, not shown, in the boss 49. A pivot 134 is provided on the L-shaped bracket 130, and that pivot extends forwardly from that bracket.

The numeral 140 denotes the bottom wall of the change-making device of the present invention, and that bottom wall is shown in FIG. 6. That bottom wall has a generally ovate discharge opening 142 in it, it has an elongated, upwardly extending rib 144 thereon, it has two upwardly extending ribs 146 thereon, and it has an upwardly extending arcuate rib 148 thereon; and that arcuate rib connects the left-hand ends of the ribs 146. As shown by FIG. 6, the arcuate rib 148 is immediately adjacent the right-hand edge of the opening 142. Two upstanding ribs 150 are contiguous with the opposite edge of the opening 142, and two openings 152 are spaced to the left of the ribs 150. A further upstanding rib 154 is provided for the bottom wall 140, and an upstanding rib 156 is disposed intermediate the rib 154 and the rear edge of the bottom wall 140. The numeral 157 denotes an upstanding flange at the right-hand edge of wall 140, the numeral 159 denotes an upstanding flange at the rear edge of that wall, and the numerals 161 and 163 denote narrow upstanding flanges at the left-hand edge of that wall. The flange 157 abuts the inner face of flange 38 on frame 30, the flanges 161 and 163 abut the inner face of the flange 40 of that frame, and the flange 159 abuts the inner face of the rear cover 113. Screws 164 suitably extend through openings in the flanges 38 and 40 and seat in drilled and tapped openings in the flanges 157, 161 and 163 to hold the bottom wall 140 fixed relative to the frame 30. The numeral 158 denotes openings in the bottom wall 140; and there are four such openings. Two of the openings 158 are located at the opposite ends of the rib 144, a third opening 158 is adjacent one end of the rib 154, and the fourth opening 158 is intermediate the ends of that rib. The ribs 144 and 154 are provided with upwardly bent annular portions that surround the openings 158. The numeral 160 denotes a notch adjacent the left-hand portion of the front edge of the wall 140, and that notch accommodates the lower end of the rejected coin chute of the change-making device. A larger notch 162 is provided adjacent the right-hand portion of the rear edge of the wall 140, and that notch accommodates the lower end of the accepted coin chute. As shown by FIGS 24 and 25, the lower face of the bot-

tom wall 140 is flush with the bottom edges of the flanges 38 and 40.

The numeral 168 denotes a resilient pad which is disposed above, and in register with, the openings 152 of bottom wall 140. An L-shaped bracket 170 rests on the top of the pad 168, and screws 172 extend downwardly through alined openings in bracket 170 and pad 168 and seat in the openings 152. The bracket 170 has two openings in the top thereof to receive the hooked ends of two helical extension springs 216.

The numeral 174 generally denotes the payout slide of the change-making device provided by the present invention, and that payout slide is different from the payout slides of said co-pending application. That slide has two elongated upstanding ribs 176 adjacent the front and rear edges thereof; and an upwardly extending rib 178 is provided at the center line of the slide 174 at the right-hand end of that slide. Two ears 180 extend upwardly from that right-hand edge of slide 174, and those ears are disposed forwardly and rearwardly of the rib 178. A pin 182 is fixedly secured within and carried by openings in the upper ends of the ears 180. Two ears 184 extend upwardly from a narrow section adjacent the left-hand end of the slide 174, and those ears have openings adjacent the upper ends thereof. Those openings fixedly carry a pin 186; and a roller 188 is rotatably mounted on that pin. Horizontally-directed ears 190 also extend from the narrow section at the left-hand end of slide 174; and those ears are offset upwardly, as shown by FIG. 11. Those ears are arcuate in cross section, and the arcuate upper surfaces of those ears enable those ears to serve as smooth bearing surfaces. A slot 194 extends from a point adjacent ears 190 to the coin-receiving opening 192 of the slide. Two of the sides of the opening 192 are generally straight and parallel, and the other two sides are concave. An inclined, coined edge 196 is provided for the right-hand edge of opening 192. A coined recess 198 is formed in the under face of the slide 174, and that recess follows the peripheries of opening 192 and slot 194. The vertical face of the opening 192 is thinner than a dime; and if a dime gets in reservoir 214, the vertical face of opening 192 will pay out the dime and the inclined edge 196 will raise the nickels thereabove and prevent a jam.

The payout slide 174 is preferably formed by a series of punch press operations; and it is preferably formed from an elongated metal strip as wide as the slide is long. Such a strip is made by shearing a large sheet of metal; and the shearing operation forms an upwardly extending burr, not shown, at the left-hand end of slide 174 while forming a downwardly extending burr 199 at the right-hand end of that slide. During the trimming, hole-forming, and other punch press operations, further burrs are formed on the slide 174; the upwardly extending burr 197 being formed at the elongated sides and inclined edges of the central part of the slide during the trimming operation, and a downwardly extending burr, not shown, being formed at the peripheries of opening 192 and slot 194 during the hole-forming operation. This latter burr is effectively eliminated by a coining operation that forms the recess 198 which extends around the peripheries of opening 192 and slot 194.

Heretofore it has been customary to employ a sanding or grinding operation to remove the downwardly extending burr 199, the downwardly extending burr at the peripheries of opening 192 and slot 194, and the burr 197; but such an operation is time-consuming and expensive. The present invention obviates all need of that sanding or grinding operation by coining away the burr at the peripheries of opening 192 and slot 194, and by providing ribs that obviate the need of removing the burrs 197 and 199. As indicated particularly by FIGS. 8 and 10, the burrs 199 and 197 are shallow in height; and those burrs are actually shallower in height than the ribs 144, 146 and 154 on bottom wall 140 and the ribs 176 on slide 174.

Consequently, the ribs 144, 146 and 154 on bottom wall 140 will engage the lower face of slide 174 and hold that lower face far enough above the wall 140 to keep the burr 199 from engaging that wall. That burr will be intermediate the two ribs 146 and will not contact any part of the bottom wall 140. The upwardly extending burr 197 and the upwardly extending burr, not shown, at the left-hand end of the slide 174 will be held below and out of engagement with the lower face of supporting plate 200 by the ribs 176 on the slide. The overall result is that the slide 174 is made without the cost and delay involved in a sanding or grinding operation.

The supporting plate 200 has a T-shaped slot 202 which receives the upstanding ears 180 on the slide 174. The head of the T-shaped slot 202 is wide enough to accommodate the full length of the pin 182 carried by those ears, but the stem of that T-shaped slot is narrow enough to prevent movement of that pin downwardly through that stem. That stem is just slightly wider than the distance between the outer faces of ears 180, and it helps guide the reciprocation of the slide. A slot 204 adjacent the left-hand end of the supporting plate 200 accommodates the upstanding ears 184. That slot is just slightly wider than the distance between the outer faces of the ears 184, and it helps guide the reciprocation of the slide. After the ears 184 have been moved upwardly into the slot 204, the pin 186 and the roller 188 thereon are assembled with those ears. That pin is held in position within the openings in the upper portions of the ears 184 by the hooking of the ends of helical extension springs 216 through openings in the ends of that pin. The roller 188 is a sleeve that can rotate relative to the pin 186.

An elongated, wire-like spring 206 has one end thereof bent to form a flattened loop; and rivets 208 extend through that loop and through openings in plate 200 to the left of the slot 204. Those rivets fixedly hold the spring 206 in position relative to the slot 204. The spring 206 has a downwardly bent projection 207 intermediate the ends thereof, and the right-hand face of that projection is inclined. As shown by FIG. 24, that projection is adjacent the discharge opening 142 in bottom wall 140; and, as shown by FIG. 7, the spring is in register with the slot 194 in slide 174. As a result, the projection 207 engages coins moved by the slide 174 and urges those coins downwardly through the discharge opening 142. The right-hand end of the spring 206 rests upon a tongue 205 which is provided at the right-hand end of the slot 204.

The numeral 210 denotes four openings in the supporting plate 200, and those openings are in register with the openings 158 in the bottom wall 140. A flange 211 is provided at the rear edge of the plate 200, and that flange extends downwardly and rearwardly toward the bottom wall 140, as shown particularly by FIG. 3. That flange stiffens the plate 211. A flange 212 extends upwardly around an opening at the center of the supporting plate 200, and that flange accommodates the lower end of a coin reservoir 214. That lower end of that coin reservoir is suitably secured to the flange 212 in a permanent manner. The coin reservoir 214 has a vertical slot 215 in the rear thereof, and that slot accommodates the feeler 118 of switch 116.

The numeral 218 denotes sleeve-like spacers that are set in alinement with the openings 158 in bottom wall 140 and with the openings 210 in supporting plate 200; and those spacers fix the spacing between the upper face of bottom wall 140 and the lower face of supporting plate 200. That spacing exceeds the thickness of slide 174 plus the combined heights of ribs 146 and 176; and hence that spacing facilitates free reciprocation of the slide 174. As the slide 174 reciprocates, the ribs 144, 146, 150 and 154 on bottom wall 140 and the ribs 176 on that slide minimize frictional resistance to that reciprocation and also keep the burrs from contacting the bottom wall 140 or the supporting plate 200. The springs 216 extend between

the openings in the ends of pin 186 and openings in the L-shaped bracket 170, and those springs bias the slide 174 for movement toward the resilient pad 168.

The numeral 222 generally denotes a lever which is rotatably mounted on the pivot 62 adjacent the left-hand side of FIG. 1. That lever has a hub 224 with an opening that telescopes over the pivot 62, it has a cam-slot 226, it has a recess 228 that accommodates a rod-like magnet 230, it has a rearwardly extending pin 232, it has an internally toothed star washer 234 on that pin, and it has an abutment 236 in the form of a pin projecting rearwardly from the rear face thereof. The star washer 234 abuts the rear face of the rod-like magnet and holds it in position within the recess 228. As indicated particularly by FIG. 13, the magnet 230, the pin 232 and the abutment 236 extend rearwardly through the opening 60 in the wall 32. That opening is large enough to permit the lever 222 to rotate from its initial position, shown by FIGS. 1 and 23, to its lowered position, shown by FIG. 25. The lever 222 differs from the corresponding lever in said co-pending application by having the magnet 230, by having the pin 232 and by having a deeper cam-slot.

The numeral 238 generally denotes a lever that also is rotatably mounted on the pivot 62 shown at the left-hand edge of FIG. 1. That lever has an opening 240 which telescopes over the pivot 62, has a cam-slot 242, has an offset ear 244 that extends downwardly below the level of the cam-slot 242, and has two inclined but generally vertically-directed abutments 246 and 248. Those abutments are at the right-hand end of that lever, as that lever is viewed in FIG. 16. When the lever 238 is rotatably mounted on the pivot 62, the ear 244 overlies, and can rest upon, the stud 66, as shown by FIG. 24; but that ear can also be raised up out of engagement with that stud, as shown by FIG. 25. Once the lever 222 has been telescoped over the pivot 62, and once the lever 238 has been telescoped over the pivot 62 and moved into engagement with the hub 224 of lever 222, a C-washer 250 can be set in a groove adjacent the forward end of pivot 62. That C-washer prevents accidental separation of those levers from that pivot. The wall 374 overlies the right-hand end of the lever 238, and thereby keeps the abutments 246 and 248 of that lever in register with the coin passageway defined by the walls 32 and 374.

The numeral 252 generally denotes an elongated lever which has an upper arm and a lower arm that coact to subtend an obtuse angle. The hub 260 of that lever telescopes over the pivot 88 which extends forwardly from the forwardly offset portion 79 of the wall 32. An ear 254 extends rearwardly from the upper portion of the upper arm of lever 252; and that ear extends through the cam-slot 226 of lever 222 and extends into the arcuate slot 76 in wall 32. A pin 256, which preferably is riveted to the upper arm of the lever 252, is located below the level of the ear 254; and that pin extends into the cam-slot 242 of the lever 238. An opening 258 is provided in the upper arm of the lever 252, and that opening receives one end of a helical extension spring 266. The other end of that spring is hooked around the stud 81 that extends forwardly from the wall 32 and is immediately adjacent the opening 78 in that wall. A C-washer 268 is set in a groove in stud 81, and that C-washer prevents accidental separation of the spring 266 from that stud; and that spring biases the lever 252 for rotation in the counterclockwise direction. A rearwardly extending offset 262 is provided in the lower arm of the lever 252, and that offset disposes the bottom of that lower arm close to the plane of the forwardly offset portion 79 of wall 32. A pin 264 extends forwardly from that rearwardly offset bottom of lever 252, and that pin rotatably supports a roller 265.

The numeral 270 denotes a latch which has an opening, not shown, at its right-hand end that telescopes over the forwardly extending portion of the hub 260 of lever 252. That opening is large enough to permit the latch 270

to rotate freely and independently of the lever 252. That latch also has a rearwardly bent portion 271 that defines a concave recess. The latch 270 inclines downwardly and to the left, as it is viewed in FIG. 25; and it has a sharp lower end. Once the opening in the latch 270 has been telescoped over the forwardly extending portion of the hub 260 of lever 252, a C-washer 272 is set in a groove in that forwardly extending portion of that hub to prevent accidental separation of latch 270 from lever 252. Thereupon, a C-washer 274 can be set in a groove in the forward end of the pivot 88, and that C-washer will prevent accidental separation of lever 252 from that pivot. The rearwardly bent portion 271 keeps the rises on the multi-lobe section of the cam from engaging and moving the latch 270.

The numeral 280 denotes the rear section of a cam which is mounted on the output shaft 94 of the motor 90. That rear section has a rise 282 succeeded by a high dwell 284, it has a low dwell 286 succeeding the high dwell 284, it has a rise 288 succeeded by an intermediate dwell, and it has a further rise 290. The portion of the periphery of the cam section 280, intermediate the rise 290 and the rise 282 constitutes a long, constant-radius dwell.

Integrally formed with the rear section 280 of the cam is a hub 302 that extends forwardly from that rear section. Also formed integrally with, and extending forwardly from, that rear section are two pins 296 and a pin 293. Formed integrally with, and projecting radially outwardly from, the rear section 280 is a circular flange 292. Also formed integrally with, and extending forwardly from, the rear section 280 is a section 294 which has a plurality of notches 295 therein. Those notches accommodate the sharp end of latch 270; and the leading edges of those notches constitute abutments against which the sharp end of latch 270 can bear. The circular flange 292 serves to keep the latch 270 in register with the notches 295 in the notched section 294 of the cam. Four recesses 298 are provided in the front face of the notched section 294; and those recesses are circumferentially spaced. Preferably, the rear section 280, the notched section 294, the flange 292, the hub 302, the pins 296, the pin 293, and the recesses 298 are formed by a die casting operation.

The pins 296 extend into two openings 316 in a multi-lobe section 304 of the cam, and the forward ends of those pins are riveted over to permanently secure the multi-lobe section 304 to the rear section and to the notched section. The pin 293 extends through and projects forwardly beyond an opening 315 in the multi-lobe section 304. That multi-lobe section has an opening at the center thereof which accommodates and telescopes over the hub 302; and it has four circumferentially spaced, tapped openings 318. Those openings are smaller than, but are in register with, the recesses 298 in the notched section 294. One pair of openings 318 is on one diameter of the multi-lobe section 304, and the other pair of openings 318 is on another diameter of that section.

The multi-lobe section 304 has a rise 306 succeeded by a convex-plano fall, has a rise 308 succeeded by a convex-plano fall, has a rise 310 succeeded by a convex-plano fall, has a rise 312 succeeded by a convex fall, and has a rise 314 succeeded by a convex-plano fall. The rise 306 has a predetermined outer radial dimension, and the outer radial dimension of the rise 308 is less than that predetermined outer radial dimension. The outer radial dimension of the rise 310 is the same as the outer radial dimension of the rise 308. The outer radial dimension of the rise 312 is greater than the outer radial dimension of the rise 306, and thus is greater than the outer radial dimension of either of the rises 308 and 310. The rise 314 has the smallest outer radial dimension of all of the rises 306, 308, 310, 312 and 314.

The numeral 320 denotes the front section of the cam,

11

and that section has a central opening that telescopes over the hub 302 of the cam. That front section has a rise 322 with an outer radial dimension that is larger than the outer radial dimension of rise 308 or rise 310 but that is smaller than the outer radial dimension of the rise 306. That front section has two large diameter openings, not shown, that are larger than, but can be set in register with the pairs of openings 318 in the multi-lobe section 304. The front section 320 of the cam also has two smaller openings 325 that are disposed on opposite sides of one of the two large openings. When the two large openings in section 320 are set in register with one of the pairs of openings 318, the pin 293 will extend into one of the openings 325 in that front section; and when those large openings are set in register with the other pair of openings 318, the pin 293 will extend into the other of the openings 325 in that front section. Screws 300 can pass through the large openings in the front section and seat in one or the other of the pairs of openings 318 in the multi-lobe section 304, thereby preventing relative rotation between the front section 320 and the rest of the cam. When the large openings of the front section 320 are set in register with one of the pairs of openings 318, the rise 322 on that front section is intermediate the rises 306 and 312, as shown by FIGS. 1 and 24; and at such time the rise 322 is immediately adjacent the rise 314. When those large openings in the front section 320 are set in register with the other pair of openings 318, the rise 322 on that front section is immediately adjacent the rise 306. The threaded shanks of the screws 300 extend into and are accommodated by the recesses 298 in the notched section 294 of the cam.

The numeral 326 generally denotes a latch which has a sleeve-like hub 327 extending rearwardly therefrom. The opening in that hub telescopes over, and is rotatably supported by, the pivot 134 carried by the L-shaped bracket 130. The latch 326 has a notch 328 therein, has a forwardly extending pin 330, has a camming surface 329, has a rearwardly offset ear 332, and has a forwardly extending pin 334 on that ear. In plan, the latch 326 is somewhat Z-shaped.

A connecting rod 336 has a slot 338 in the lower portion thereof, has a slot 340 adjacent the bottom thereof, has an opening 342 above the slot 338, and has an opening 343 at the top thereof. The slot 340 telescopes over the pin 334 on the ear 332 of latch 326; and a helical extension spring 344 has the lower end thereof set in a peripheral groove in the forward end of the pin 334. The upper end of the spring 344 is hooked in the opening 342 of connecting rod 336, and that spring normally holds the pin 334 at the upper end of the slot 340. One end of a helical extension spring 346 is hooked in the opening 342 of connecting rod 336, and the other end of that spring is hooked in an opening in the plate 68 on wall 32. The spring 346 biases the connecting rod 336 upwardly, and thereby biases the latch 326 for rotation in the clockwise direction. The connecting rod 336 differs from the corresponding connecting rod in said co-pending application by having the slot 340 and the spring 344 which provide a lost-motion connection between latch 326 and connecting rod 336.

The numeral 348 generally denotes a coin-responsive element which has an opening 350 that telescopes over the pivot 52 which projects forwardly from the wall 32 at a point above the accepted coin chute 42. That coin-responsive element has a pin 352 extending forwardly therefrom, and it has a recess 351 adjacent the pin 352. That pin telescopes through the opening 343 at the top of the connecting rod 336 and thereby interconnects that connecting rod and that coin-responsive element. A pin 354 also projects forwardly from the coin-responsive element 348, and a pin 356 projects rearwardly from that element. The pin 356 extends through the opening 64 which is in the wall 32 and which is disposed above and to the left of the pivot 52; and that pin engages the right-

12

hand edge of the opening 64 to limit clockwise rotation of the coin-responsive element 348. The coin-responsive element has a coin-holding portion 358 and has a coin-feeling portion 360 located above the level of the coin-holding portion 358. The coin-responsive element 348 also has a surface 359 thereon, adjacent the upper left-hand edge thereof, that selectively approaches the abutments 246 and 248 on the lever 238. A C-washer, not shown, will fit in the groove 353 in the pin 352 to prevent accidental separation of the connecting rod 336 from that pin 352, and thus from the coin-responsive element 348. That coin-responsive element is similar to the corresponding coin-responsive element in said co-pending application, but the coin-feeling portion 360 inclines to the left rather than to the right on that coin-responsive element.

The numeral 364 generally denotes a second coin-responsive element; and that coin-responsive element has an opening 366 which telescopes over the pivot 52 to cause the coin-responsive elements 348 and 364 to rotate concentrically. A slot 368 is provided in the coin-responsive element 364, and that slot telescopes over the pin 354 which extends forwardly from the coin-responsive element 348. An opening 367 is also provided in the coin-responsive element 364, and that opening telescopes over the pin 352 carried by the coin-responsive element 348. The pins 352 and 354 coat with opening 367 and slot 368 to cause the two coin-responsive elements to rotate together as a unit. A coin-holding and coin feeling surface 370 is provided adjacent the upper end of the coin-responsive element 364.

Referring to FIG. 3, the numeral 374 denotes a partition or wall which is spaced forwardly of the wall 32 by the bosses 31, 33, 35 and 37 on the front face of the wall 32. The partition or wall 374 coats with the wall 32, with the flange 38, and with the bosses 31, 33, 35 and 37 to define a passageway for a quarter. The inlet of that passageway will be below and in register with the quarter outlet of the slug rejector, and the outlet of that passageway will be above and in register with the inclined portion of the accepted coin chute 42. That passageway will force each accepted quarter to engage the switch actuators 110 and 192 of the switches 106 and 96, respectively; and as that quarter engages and moves past those switch actuators, that quarter will cause those actuators to shift the contacts of those switches from normal position to actuated position and then free those contacts for return to normal position.

The partition or wall 374 has an upper arcuate slot 372 which accommodates the transversely-directed, coin-receiving portion of the switch arm 110; and it has a lower arcuate slot 373 which accommodates the transversely-directed, coin-receiving portion of the switch arm 192. That partition or wall also has an arcuate notch 375 which accommodates the forwardly extending pin 354 on the coin-responsive element 348. Further, the wall 374 has three projections 377 at its right-hand edge; and those projections extend through three openings in the flange 38. The interaction between the projections 377 and those openings in the flange 38 fixedly holds the right-hand edge of the wall 374 relative to the frame 30.

The numeral 376 denotes a partition or wall which is disposed to the left of the wall 374 in FIG. 3; and the wall 376 has a number of bosses which extend to the right in FIG. 3 and abut the left-hand face of the wall 374; and those bosses are shown by cross hatching in FIGS. 23-25. The numeral 378 denotes an inclined upper face on the boss at the right-hand side of the wall 376, the numeral 380 denotes a concave surface that is on that boss and is disposed below the level of, but contiguous with, the inclined surface 378, and the numeral 382 denotes a second concave surface on that boss which coats with the concave surface 380 to define a cusp. A third concave surface 384 is provided on that boss, and it forms an almost imperceptible cusp with the concave surface 382.

An inclined surface 386 on that boss coacts with the concave surface 384 to define a cusp-like projection; and a vertical surface on that boss extends downwardly from the inclined surface 386. A reversely inclined surface 390 is provided at the bottom of the vertical surface 386. A reversely inclined surface 390 is provided at the bottom of the vertical surface 388, and a second vertical surface 392 extends downwardly from the inclined surface 390. Another boss at the rear surface of the wall 376 has a concave face 394 adjacent the top thereof, has a second concave face 396 which coacts with the first concave surface 394 to form an almost imperceptible cusp, has a third concave surface 398 that coacts with the concave surface 396 to form a more perceptible cusp, and has a concave surface 400 that coacts with the concave surface 398 to perform a very perceptible cusp. A vertical surface 402 extends downwardly below the level of the concave surface 400, and that vertical surface terminates at a point above the level of the top of the coin-responsive element 364. The third boss at the rear face of the wall 376 is denoted by the numeral 404, and it is shown particularly by FIGS. 24 and 25. That boss is horizontally directed, and it has an opening through it which accommodates a fastener 406. The wall 376 has two arcuate slots, not shown, that are identical to and are in register with the arcuate slots 372 and 373 in the wall 374.

The wall 376 and the two vertically directed bosses thereon coact with the wall 374 to define a passageway for dimes; and the inlet of that passageway is below and in register with the dime outlet of the slug rejector, and the outlet of that passageway is above and in register with the inclined portion of accepted coin chute 42. An accepted dime entering that passageway will be forced to move past the two arcuate slots and to move the switch arms 110 and 102 downwardly. In so moving those switch arms, that dime will cause the contacts of the switches 106 and 96 to shift from their normal position to actuated position; and as that dime passes out of engagement with the switch arms 110 and 102, those switch arms will be freed for movement toward normal position.

The wall 376 coacts with a paration or wall 416 to define a passageway for nickels. The walls 374, 376 and 416 are substantially identical to the corresponding walls in said co-pending application, and they perform the same functions.

The left-hand edges of the walls 416 and 376 are held rigid relative to the wall 32 of frame 30 by screws 418 and 405, shown in FIG. 1. Further, the right-hand edge of the wall 416 is held fixed relative to the frame 30 by three projections 408 which seat in three vertically aligned openings in the flange 38.

The numeral 410 generally denotes a strip of metal that constitutes a liner for the inclined front portion of the accepted coin chute 42; and that strip of metal also fixes the forwardmost vertical wall of that chute. The upper end of the metal strip 410 is provided with two ears 409 which are bent forwardly and downwardly to have a configuration comparable to the uppermost edge of the inclined portion of the coin chute 42, as shown particularly by FIG. 3. Those ears extend far enough to underlie part of the front face of the inclined portion of the accepted coin chute 42, and hence they serve to anchor the upper end of the metal strip 410 relative to the coin chute 42.

The metal strip 410 has an angle approximately one hundred and thirty five degrees in it at a point below the lowermost part of the inclined portion of accepted coin chute 42. That metal strip also has a right angle bend at the level of the bottom surface of bottom wall 140; and the bottom 411 of the metal strip 410 extends forwardly from that right angle bend. A slot, not shown, is provided in the bottom 411, and one of the screws 220 extends upwardly through the said slot and has its head underlying those portions of the bottom 411 which define that slot. Consequently, that screw fixedly secures

the metal strip 410 in position relative to the change-making device.

The numeral 414 denotes the rejected coin chute provided for the change-making device of the present invention. With the exception of the arcuate notch 415 in the right-hand edge of that coin chute, that chute is identical with the corresponding rejected coin chute in said co-pending application. The lower end of the rejected coin chute 414 has a horizontally extending flange 412, and that flange has a slot therein which accommodates the shank of another of the screws 220. As a result, the head of that other screw underlies those portions of the flange 412 which define the notch and thereby clamp that flange tightly against the bottom wall 140 of the change-making device.

The numeral 420 denotes a coin guide that is held for rotation adjacent the top of the coin reservoir 214 by the screw 424; and that screw also holds one side of the coin inlet 422 for the coin reservoir 214. The other end of that coin inlet is held by the screw 426. Nickels leaving the passageway defined by the walls 416 and 376 pass between the two upstanding ears of the coin guide 420 and move downwardly through the coin inlet 422 to enter the coin reservoir 214.

25

Normal Position of Components

The normal position of the components of the change-making device provided by the present invention is indicated by FIG. 1; and, in that position, the coin-responsive elements 348 and 364 intercept quarters and dimes respectively. Also, in that position, the rear section 280 of the cam has its low dwell 286 adjacent the roller 265 on the lower arm of lever 252. Further, in that position, the rise 322 on the front section 320 of the cam is engaging the roller 188 carried by the pin 186 of the payout slide, and that rise is coacting with the convex fall succeeding the rise 312 to hold that slide with its coin-receiving openings 192 below and in register with the outlet of the coin reservoir 214. Additionally, in that position, the pin 182 held by the ears 180 on payout slide 174 are in engagement with the camming surface 329 on the latch 326, and that pin is holding the notch 328 on that latch up and out of register with the pin 182. Moreover, in that position, the switch arms 110 and 102 are adjacent the upper ends of the arcuate slots 372 and 373, respectively. Furthermore, the lever 222 has its abutment 236 above and out of engagement with the switch arm 102, and the lever 238 has its ear 244 resting upon the stud 66.

50

If an adequate supply of nickels is in the coin reservoir 214, those nickels will be holding the feeler 118 against full entry into the slot 215 at the rear of coin reservoir 214. This enables the switch 116 to energize a lamp in the vending machine which is associated with a sign indicating that nickels, dimes and quarters can be accepted. That lamp will remain illuminated as long as the number of nickels in the reservoir 214 is sufficient to block full entry of the feeler 118 into the coin reservoir 214 through the slot 215; and the feeler 118 is made short enough to require at least four nickels to be in the reservoir 214. In actual practice, the feeler 118 is made short enough to require more than seven nickels to be in the reservoir 214 to prevent full entry of the feeler 118. When the supply of nickels in the reservoir 214 falls below the prescribed number, the feeler 118 will move inwardly through the slot 215 in that reservoir and cause the switch 116 to deenergize the first said lamp and to energize a lamp adjacent a sign indicating that coinage equalling the sales price must be inserted. The feeler 118 and the switch 116 perform the functions which the corresponding feeler and switch perform in the said co-pending application. Throughout the rest of this description it will be assumed that sufficient nickels are in the coin reservoir 214 to hold the feeler 118 against full entry through the slot 215.

75

Nickel Operation

If a nickel is introduced into the coin slot of the vending machine, that nickel will pass through the slug rejector and be delivered to the passageway defined by the walls 416 and 376. That nickel will engage the switch arm 110 as it moves downwardly through that passageway, and will move the switch arm 110 downwardly toward the lower end of the slot 372. Thereafter that nickel will continue on to the bottom of that passageway. If the reservoir 214 is not full, that nickel will enter, and come to rest in, that reservoir. However, if the reservoir is full, that nickel will engage a nickel held by the guide 420 and be deflected to the right where it will then fall downwardly into the accepted coin chute 42. A suitable conduit, not shown, will extend between the bottom of the accepted coin chute and the cash box of the vending machine.

As the switch arm 110 was moved downwardly by the nickel, it caused the switch 106 to send an impulse to the vending machine. That impulse will start the vending cycle of the vending machine, and the electrical circuit of the vending machine will cause that vending machine to pass through one complete cycle. The nickel did not move the switch arm 102 because that arm does not extend into the passageway defined by the walls 416 and 376.

Dime Operation

If a dime is introduced into the coin slot of the vending machine, that dime will pass through the slug rejector and enter and move downwardly through the passageway defined by the walls 374 and 376. In moving downwardly through that passageway, that dime will be deflected to the left by the concave surface 380 and force the switch arm 110 to move downwardly toward the lower end of the slot 372; thereby sending an impulse to the vending machine to cause that vending machine to start its cycle of operation. The arcuate surface 394 permits this left-hand movement of the dime; and the arcuate surfaces 396 and 398 start that dime moving back toward the right. The arcuate surface 382 accommodates this right-hand movement of the dime; and the arcuate surface 384 then starts that dime moving back to the left. That dime will thus be caused to engage the switch arm 102 and move that switch arm downwardly toward the lower end of the arcuate slot 373. As the switch arm 102 approaches the lower end of the arcuate slot 373, it will be attracted to and held by the magnet 230 on the lever 222. When the switch arm 102 is so attracted and held, it is below and out of engagement with the dime, which has meanwhile come to rest on the upper face of the coin-responsive element 364, as shown particularly by FIG. 23. Hence, even though the dime is out of engagement with the switch arm 102, that switch arm is held in switch-actuating position and actuates the switch 96. The actuation of switch 96 energizes the motor 90, and that motor rotates the output shaft 94 in the counter clockwise direction, as that shaft is viewed in FIGS. 1 and 20-25.

That counter clockwise rotation of that shaft enables the rise 322 on the front section 320 of the cam to act through the roller 188, the pin 186 and the ears 184 to move the payout slide 174 to the right; and such movement acts through the camming surface 329 to rotate the latch 326 in the counter clockwise direction. That counter clockwise rotation of latch 326 acts through the pin 334 and the spring 344 to pull downwardly on the connecting rod 336 and thereby rotate the coin-responsive elements 348 and 364 in the counter clockwise direction. Before the rise 322 on the front section 320 of the cam moves out of engagement with the roller 188 carried by the pin 186, that rise will have acted through the slide 174 and the latch 326 to rotate the coin-responsive elements 348 and 364 far enough in the counter clockwise direction to move the surface 359 on coin responsive element 348 into abutting engagement with

the abutment 248 on lever 238. That engagement prevents further counter clockwise rotation of the coin-responsive elements 348 and 364, but that rotation has been great enough to permit the dime to move downwardly into engagement with the coin-feeling and coin-holding surface 370 on the coin-responsive elements 364.

Also before the rise 322 moves out of engagement with the roller 188, that rise will have caused further counter clockwise rotation of the latch 326. Such rotation can not rotate the coin-responsive elements 348 and 364 further in the counter clockwise direction because of the engagement of surface 359 on coin-responsive element 348 with the abutment 248 on lever 238, and hence that further counter clockwise rotation of the latch 326 merely stretches the spring 344. The slot 340 in the connecting rod 336 accommodates that further counter clockwise rotation of the latch 326 by enabling the pin 334 to move downwardly relative to the connecting rod 336. That further movement of the latch 326 will be very limited, and hence the consequent downward movement of the pin 334 will be amply accommodated by the slot 340 in connecting rod 336.

As the rise 322 moves past and out of engagement with the roller 188 on pin 186, that roller will engage the convex part of the convex-plano fall which succeeds that rise; and that convex part will permit the slide 174 to start moving to the left. That movement of the slide 174 will enable the cam surface 329 on latch 326 to respond to the forces of spring 346 and 344 to move downwardly relative to the pin 182 carried by the ears 180 on slide 174. The resulting clockwise rotation of the latch 326 will free the coin-responsive elements 348 and 364 for rotation in the clockwise direction under the action of spring 346; but the dime, in the passageway defined by the walls 374 and 376, will be intermediate the coin-feeling and coin-holding surface 370 of coin-responsive element 364 and the vertical surface 388 of the boss on wall 376. Consequently, little or no clockwise rotation of the coin-responsive elements will be experienced at this time. As a result, the latch 326 will be held in the position indicated by dotted lines in FIG. 24; and, in that position, the notch 328 on that latch is above the level of, and out of register with, the pin 182 carried by the ears 180 on slide 174. Thereafter, when the further counter clockwise rotation of the shaft 94 moves the plane part of the convex-plano fall on the front section 320 of the cam adjacent the roller 188 carried by the pin 186, the slide 174 will respond to the forces of springs 216 to pull the slide from coin-loading position to coin-discharging position. In the latter position, the opening 192 of the slide 174 is in register with the discharge opening 142 of the bottom wall 140; and the nickel in the opening 192 of the slide 174 will fall downwardly through the discharge opening 142. That nickel will pass into a conduit, not shown, which will lead to a coin cup at the exterior of the vending machine; and it can then be removed from that cup by the patron. That nickel will be urged downwardly and out of the opening 192 in the slide 174 and downwardly and out of the opening 142 by the inclined right-hand side of the projection 207 intermediate the ends of spring 206. The limit of the left-hand movement of the slide 174 is determined by the engagement of the left-hand end of that slide with the resilient pad 168. The discharge nickel is, of course, required change where a dime is inserted and the sales price is five cents.

Almost simultaneously with the freeing of slide 174 for movement to coin-discharging position, the rise 288 on the rear section 280 of the cam engages the roller 265 carried by the pin 264 on the lower arm of lever 252. That rise responds to further counter clockwise rotation of the shaft 94 to rotate the lever 252 in the clockwise direction, and that rotation of lever 252 moves the ear 254 to the right in the cam-slot 226. The rotation of the lever 252 by the rise 288 is not extensive,

prior to the time the rise 306 on the multi-lobe section 304 of the cam engages the roller 188; but that rotation is great enough to move the ear 254 out of engagement with the left-hand end of the cam-slot 226; and, therefore, the lever 222 is freed for rotation, under the action of gravity, downwardly toward the stud 58. However, the flux lines from the magnet 230 are strong enough to enable that magnet to hold itself in engagement with the switch arm 102, which is adjacent the lower end of the arcuate slot 373; and this means that the lever 222 will remain in an intermediate position close to its initial, raised position. As a result, at the time the rise 306 engages the roller 188, the lever 222 has rotated only a short distance downwardly from its initial, raised position.

Further counter clockwise rotation of the shaft 94 causes the rise 306 to move the slide 174 to the right, and causes the rise 288 to rotate the lever 252 far enough in the clockwise direction to move the ear 254 into engagement with the convex portion of the cam-slot 226 in lever 222; and the engagement of that ear with that convex portion forces the lever 222 to rotate far enough in the clockwise direction to produce an air gap between the magnet 230 and the switch arm 102. Thereupon, the lever 222 will drop downwardly to the position shown by FIG. 25; and in that position that lever rests upon the stud 58. The lever 222 will drop downwardly very rapidly, and the abutment 236 thereon will engage and hold down the arm 102 of the switch 96, thereby keeping that switch arm from returning to switch-restoring position. The downward movement of the lever 222 is so rapid that the motor 90 operates as though the switch arm 102 did not move upwardly at all.

The movement of the slide 174 to the right by the rise 306 moves the coin-receiving opening 192 toward the coin reservoir 314, but before that opening has been placed in register with the coin reservoir 214 to receive another coin, a notch 295 of the notched section 294 of the cam has moved under the pointed end 269 of the latch 270. Thereupon, reverse rotation of the cam is prevented even if someone were to shut off the power by pulling the vending machine's plug out of the wall socket. Hence, even if someone deliberately removed the vending machine's plug from the wall socket to remove the electro-motive force from the shaft 94 and to enable the springs 216 to cause the slide 274 and the pin 186 thereon to start the cam rotating in the reverse direction, that reverse direction could not be hurtful. Any such reverse rotation prior to the time the said notch 295 passes under the sharp end of latch 270 can not be hurtful because the slide 174 will not have been moved far enough to the right to receive a nickel from the coin reservoir 214—and the movement of the empty slide to coin-discharging position can neither pay out an extra nickel nor move the slide out of register with rise 306; and any such reverse rotation after the notch passes under the sharp end of latch 270 can not be hurtful because it is stopped before the slide can reach coin-discharging position. As a result the removal and the re-insertion of the vending machine's plug will merely delay and can not cheat the operation of the change-making device.

Before the rise 306 on the multi-lobe section 304 of the cam can move the slide 174 far enough to the right to cause the pin 182 to engage the latch 326—held in the dotted line position of FIG. 24 by the engagement of coin-feeling portion 370 of coin-responsive element 364 with the dime—the rise 290 on the rear section 280 of the cam engages the roller 265 on the lower arm of lever 252 and rotates that lever further in the clockwise direction. That further rotation of lever 252 moves the pin 256 on the upper arm of lever 252 into engagement with the inclined surface at the right-hand side of the cam-slot 242 of lever 238 and starts rotating that lever in the counter clockwise direction. About the time the rise 306 has moved the slide 174 far enough to the right to move the

pin 182 into engagement with the camming surface 329 on the raised latch 326, the rise 290 has enabled the pin 256 to rotate lever 238 far enough in the counter clockwise direction to raise the abutment 248 upwardly and out of register with the surface 359 on the coin-responsive element 348. At such time, the abutment 246 on the lever 238 is in register with the surface 359 on the coin-responsive element 348.

Continued counter clockwise rotation of the shaft 94 enables the rise 306 to move the slide 174 far enough to the right to enable the pin 182 to rotate the latch 326 further in the counter clockwise direction to the position shown by FIG. 25. At this time, the pin 334 has moved far enough downwardly to act through the spring 344 to place the surface 359 of coin-responsive element 348 in engagement with the abutment 246 on lever 238; and, in fact, that pin can move downwardly and out of engagement with the upper end of the slot 340. In moving upwardly from its initial position where its abutment 248 limits the counter clockwise rotation of the coin-responsive elements to the intermediate position of FIG. 25 where its abutment 246 limits the counter clockwise rotation of the coin-responsive elements, the lever 238 permitted the coin-responsive element 364 to move far enough in the counter clockwise direction to enable the dime to fall downwardly past the coin-holding and coin-feeling surface 370 and to move to the accepted coin chute 42. The gauging action of the lever 238 plus the overtravel of latch 326, made possible by the lost-motion connection between that latch and connecting rod 336, makes certain that while the coin-responsive elements 348 and 364 move far enough in the counter clockwise direction to enable dimes and quarters to move successively downwardly to coin-feeling and coin-freeing positions, those coin-responsive elements can not move so far in the counter clockwise direction that dimes and quarters are released prematurely.

After the dime has moved downwardly past the coin-feeling and coin-holding surface 370 on coin-responsive element 364, the further counter clockwise rotation of the shaft 94 moves the rise 306 beyond and out of engagement with the roller 188; and thereafter the convex part of the convex-plano fall succeeding that rise will let the latch 326 rotate in the clockwise direction. That rotation places the notch 328 in the path of the pin 182; and although the plane part of that convex-plano fall frees the slide 174 for movement toward coin-discharging position, the notch 328 on latch 326 prevents such movement. Hence, further counter clockwise rotation of the shaft 94 will not permit further nickels to be paid out.

During the subsequent, continued counter clockwise rotation of shaft 94, and prior to the time the rise 308 on the four-lobe section 304 of the cam moves into engagement with the roller 188 on the slide 174—which roller is held adjacent the position of FIG. 1—a second notch 295 in the notched section 294 of the cam will pass under the sharp end 269 of latch 270. The interaction of that second notch 295 and the pointed end 269 of latch 270 is not significant during the dime operation of the change-making device because the slide 174 is already solidly latched against movement to coin-discharging position by the engagement of the notch 328 of latch 326 with the pin 182 of the slide. However, the interaction of that second notch 295 and the pointed end 269 of lever 270 is significant in the quarter operation of the change-making device, as is brought out hereinafter.

The rise 308 will act through the roller 188 on the pin 186 to move the slide 174 far enough to the right to rotate the latch 326 to slide-freeing position. However, further counter clockwise rotation of the shaft 94 will not lead to the paying out of another nickel because the coin-responsive elements 348 and 364 are not held in their left-hand positions by coins and, therefore, are free to rotate to their right-hand positions and permit the notch 328 on the latch 326 to move into the path of, and to

block movement of, the pin 182 on the slide 174. Because the rise 308 does not have an outer radial dimension as great as that of rise 322 or rise 306, the coin-responsive elements 348 and 364 are not rotated as far in the counter clockwise direction as they were rotated when rise 322 or rise 306 engaged the roller 188. However, the rise 308 did move the roller 188 far enough to cause the slide 174 to rotate the latch 326 to slide-freeing position.

Further counter clockwise rotation of the shaft 94 moves the rise 310 on the four-lobed section 304 of the cam into engagement with the roller 188 on the slide 174. Shortly before that rise engages that roller, which roller is adjacent the position shown by FIG. 1, a third notch 295 of the notched section 294 of the cam passes under and engages the sharp end 269 of the cam 70. As was the case with the second notch 295 of the notched section 294, the interaction of the third notch 295 with the pointed end 269 of latch 270 is not significant in the dime operation of the change-making machine. However, the interaction of that third notch 295 with the sharp end 269 of latch 270 is significant in the quarter operation of the change-making machine, as is explained hereinafter. Continued counter clockwise rotation of the shaft 94 will enable the rise 310 to engage the roller 188 and shift the slide 174 to the right to cause the pin 182 to act on the camming surface 329 of latch 326 and rotate that latch to slide-freeing position. However, because no coin is holding the coin-responsive elements 348 and 364 in their left-hand positions, those coin-responsive elements will move to their right-hand positions and thereby permit the latch 326 to move its notch 323 to slide-latching position as the rise 310 passes out of engagement with the roller 188. The rise 310, like the rise 308, has a shorter outer radial dimension than rise 322 or rise 306; and hence, the rise 310 will not rotate the coin-responsive elements 348 and 364 as far in the counter clockwise direction. However, the rise 310 will rotate the latch 326 to slide-freeing position.

Further counter clockwise rotation of the shaft 94 moves the rise 312 on the four-lobe section 304 of the cam toward the roller 188 and moves the rise 282 on the rear section 280 of the cam toward the roller 265 at the lower end of the lower arm of the lever 252. That latter rise then rotates the lever 252 still further in the clockwise direction and moves the pin 256 on the upper arm of lever 252 adjacent the right-hand end of the cam-slot 242 of lever 238. Such movement of the pin 256 raises the lever 238 to its fully raised position, and in that position, the lever 238 has its abutment above the level of the top of coin-responsive element 348. Further counter clockwise rotation of the shaft 94 moves the rise 282 out of engagement with the roller 265 on the lower arm of the lever 252, but the high dwell 284 on the rear section 280 of the cam holds the lever 252 in its full clockwise position, and thereby holds the lever 238 in its fully raised position. A concave notch can be provided to the left of the abutment 248 on lever 238, as shown by FIGS. 16, to permit the lever 238 to move to fully raised position without engaging and slightly raising the lever 222. However, such a notch is not necessary because the small raising of the lever 222, by an un-notched lever 238, could not move the abutment 236 on lever 222 far enough upwardly to permit the switch arm 102 to move into switch-restoring position.

After the rise 282 has moved the lever 252 to its full clockwise position, the fourth notch 295 of the notched section 294 will move under the sharp end 269 of the latch 270. As in the case of the movement of the second and third notches 295 under the sharp end 269 of the latch 270, the movement of the fourth notch 295 under the pointed end 269 of latch 270 is not significant in the dime operation but is significant in the quarter operation, as is explained hereinafter.

Further counter clockwise rotation of the shaft 94 will move the rise 312 on the multi-lobe section 304 into

engagement with the roller 188 on the slide 174; and that rise will act through roller 188 and pin 182 on the slide 174 to rotate the latch 324 far enough to rotate the coin-responsive element 348 to its full counter clockwise position. In moving to that position, the coin-responsive element 348 moves the surface 359 thereon below and to the left of the abutment 246 on lever 238. This movement of the coin-responsive element 348 is not significant in the dime operation of the change-making device but it is significant in the quarter operation of that device, as is explained hereinafter. During that movement of the coin-responsive element 348, the high dwell 284 on the rear section 280 of the cam continued to hold the lever 252 in its full clockwise position and enabled that lever to hold the lever 238 in its fully raised position.

As the rise 312 moves beyond the roller 188, the slide 174 starts to move to the left, but it is quickly held against movement to coin-discharging position by the engagement of the notch 323 of latch 326 with the pin 182 on the slide. Before that engagement occurs, the high dwell 284 on the rear section 280 moves out of engagement with the roller 265 on the lower arm of lever 252; and thereupon the spring 266 starts rotating the lever 252 in the counter clockwise direction. That rotation moves the pin 256 on lever 252 to the left in the cam-slot 242 of lever 238 and permits that lever to start rotating in the clockwise direction; and before the shaft 94 has rotated far enough in the counter clockwise direction to move the rise 322 on the front section 320 of the cam into engagement with the roller 188 of the slide 174, the spring 266 will have pulled the lever 252 to the position shown by FIG. 1. In moving to that position, the lever 252 places its ear 254 adjacent the left-hand end of the cam-slot 226 of lever 222 and thereby forces that lever to rotate to the raised position shown by FIG. 1. Also, the pin 256 on the lever 252 moves adjacent the left-hand end of the cam-slot 242 of the lever 238, thereby enabling that lever to rotate downwardly until its ear 244 rests upon and is held by the stud 66 on the wall 32. As the lever 222 is raised to its upper position, it permits the spring within the switch 96 to return the switch arm 102 to the upper end of the arcuate slot 373; and thereupon the contacts of that switch return to normal position and de-energize the motor 90. However, the slide 174 did not stop moving to the left; instead, that slide responded to the pull of the springs 216 to move to the left until the roller 188 engaged the rise 322 on the front section 320 of the cam and rotated that cam far enough in the reverse direction to bring the convex fall, succeeding the rise 312 into engagement with the roller 188. At such time, the components of the change-making device are again in the normal position, indicated by FIG. 1.

During the dime operation, an impulse was sent to the vending machine by the switch 106, and one nickel was discharged by the payout slide 174. As indicated above, the slide 174 was caused to move to the right and to move the latch 326 to slide-freeing position by each of the rises 322, 306, 308, 310 and 312 during the dime operation of the change-making device, but only the rise 322 enabled the slide to move to coin-discharging position. When the rises 306, 308, 310 and 312 caused the slide 174 to move the latch 326 to slide-freeing position, no coin held the coin-responsive elements in their left-hand positions and hence those coin-responsive elements were free to move to their right-hand positions and permit the latch 326 to move into slide-latching position.

Quarter Operation

If a quarter is inserted in the coin slot of the vending machine, that quarter will pass through the slug rejector and be delivered to the passageway defined by the wall 32 and the wall 374. The boss 31 will direct that quarter to the left and cause it to engage the switch arm 110 and move that switch arm downwardly, thereby enabling the switch 106 to send an impulse to the vending machine.

The boss 37 will force the quarter to move back to the right, and then the boss 33 will force the quarter to move to the left once again; and, in so moving, the quarter will engage the switch wire 102 and move it downwardly toward the bottom of arcuate slot 373. As the switch arm 102 approaches the lower end of the slot 373, it will be attracted to the magnet 230 and will be pulled downwardly and away from the quarter, which will come to rest on the top of the coin-responsive element 348, as indicated by FIG. 23.

The downward movement of the switch arm 102 will, as in the dime operation, energize the motor 90; and that motor will start the shaft 94 rotating in the counter clockwise direction. The rise 322 on the front section 320 of the cam will move the roller 188 to the right and thereby cause the slide 174 to rotate the latch 326 to slide-freeing position. As the latch 326 so rotates, it will act through the spring 344 and the connecting rod 336 to rotate the coin-responsive element 348 in the counter clockwise direction until the surface 359 on that coin-responsive element engages and is held by the abutment 248 on lever 238, as shown by FIG. 24. At this time, the quarter will be able to move downwardly until it is held by the coin-holding surface 358 on the coin-responsive element 348. As the rise 322 on the front section 320 of the cam continues to move the roller 188 to the right, the latch 326 will be rotated still further in the counter clockwise direction; and the slot 340 and the spring 344 will accommodate that additional rotation.

Further counter clockwise rotation of the shaft 94 moves the rise 322 out of engagement with the roller 188 and permits the roller 188 to engage the convex part of the convex-plano fall that succeeds the rise 322; and thereupon the slide 174 is free to start moving to coin-discharging position, because the quarter is holding the latch 326 in raised position. The continued counter clockwise rotation of the shaft 94 moves the plane part of the convex-plano fall, succeeding the rise 322, adjacent the roller 188; and thereupon the slide 174 moves to coin-discharging position and pays out one nickel.

Almost simultaneously with the freeing of slide 174 for coin-discharging movement, the rise 288 on the rear section 280 of the cam starts rotating the lever 252 in the clockwise direction; and that rotation enables the lever 222 to start rotating downwardly. However, as described in connection with the dime operation, the magnetic flux lines from the magnet 230 hold the lever 222 in an intermediate raised position.

Further counter clockwise rotation of the shaft 94 enables the rise 306 to engage the roller 188 and move the slide 174 to the right, and enables the rise 288 to move the lever 252 further in the clockwise direction. That further rotation of lever 252 causes the ear 254 thereon to engage the convex portion of the cam-slot 226 and force the lever 222 to rotate downwardly. Once this further clockwise rotation of lever 222 creates an air gap between magnet 230 and switch arm 102, the lever 222 quickly falls all the way down to the position shown by FIG. 25. As in the case of the dime operation, the downward movement of the lever 222 is so rapid that the switch arm 102 does not have a chance to move upwardly to stop the motor 90.

Before the rise 306 has moved the slide 174 far enough to the right to place the coin-receiving opening 192 in register with the coin reservoir 214, the first notch 295 of the notched section 294 moves into engagement with the sharp end 269 of latch 270. That engagement prevents undue reverse rotation of the cam, all as explained above.

Before the rise 306 can move the slide 174 far enough to the right to cause pin 182 to engage the raised latch 326, the rise 290 on the rear section 280 of the cam moves into engagement with the roller 265 on the lower arm of lever 252 and rotates that lever still further in the clockwise direction. That rotation moves the pin 256

against the inclined surface at the right-hand side of the cam-slot 242, thereby rotating the lever 238 in the counter clockwise direction and raising the abutment 248 upwardly and out of the path of the surface 359 on coin-responsive element 348. At such time, the abutment 246 is in register with the surface 359 of coin-responsive element 348. Consequently, when the rise 306 causes the latch 326 to rotate the coin-responsive element 348 in the counter clockwise direction, the surface 359 on that coin-responsive element can, and does, move adjacent the abutment 246 on the lever 238. Such movement of the coin-responsive element 348 is not significant in the quarter operation of the change-making device, but it was significant in the dime operation of that device because it enabled the dime to move downwardly past the coin-feeling and coin-holding surface 370 on the coin-responsive element 364.

Continued counter clockwise rotation of the shaft 94 moves the rise 306 past and out of engagement with the roller 188 on the slide 174; and it subsequently moves the plane part of the convex-plano fall, succeeding the rise 306, adjacent the roller 188. At this time, the latch 326 is held in slide-freeing position by the engagement of the coin-feeling surface 360 on the coin-responsive element 348 with the quarter; and, consequently, the slide 174 again moves to its coin-discharging position and pays out a second nickel.

Further counter clockwise rotation of the shaft 94 moves the rise 308 into engagement with the roller 188, and starts the slide 174 moving toward coin-loading position. Before that slide can reach coin-loading position, the second notch 295 of the notched section 294 of the cam moves under the sharp end 269 of the latch 270; and this means that after the slide 174 has been moved to coin-loading position but before the rise 308 and the convex part of the convex-plano fall therebehind have moved out of engagement with the roller 188, any de-energization of the motor will not lead to the paying out of an extra nickel.

Continued counter clockwise rotation of the shaft 94 enables the rise 308 to move the slide 174 to a position where it could move the latch 326 to slide-freeing position; but that latch is already in slide-freeing position because the quarter is being held and felt by the coin-responsive element 348. Consequently, when the rise 308 and the convex part of the convex-plano fall therebehind move beyond the roller 188, the slide 174 will be able to move to the left-hand end of its path of reciprocation and pay out a third nickel.

Further counter clockwise rotation of the shaft 94 will move the rise 310 into engagement with the roller 188 on the slide 174, and start that slide moving to the right. Before that slide can move its opening 192 into register with the coin reservoir 214, the third notch 295 of the notched section 294 of the cam will move under the sharp end 269 of latch 270. This means that after the slide 174 has moved far enough to pick up a fourth nickel, the de-energization of the motor 90 can not lead to the paying out of an extra nickel.

Continued counter clockwise rotation of the shaft 94 will enable the rise 310 to move the slide to a position where it could move the latch 326 to slide-freeing position. However, that latch is already in slide-freeing position because the quarter is being held and felt by the coin-responsive element 348. Consequently, when the rise 310 and the convex part of the convex-plano fall therebehind move out of engagement with the roller 188 on the slide 174, that slide will move to the left-hand end of its path of reciprocation and pay out a fourth nickel.

Continued counter clockwise rotation of the shaft 94 moves the rise 312 into engagement with the roller 188 on the slide 174 and starts that slide moving to the right. Shortly after the rise 312 engages the roller 188, the rise 282 on the rear section 280 of the cam engages the roller 265 on the lower arm of lever 252 and starts that lever

moving further in the clockwise direction. That further rotation of lever 252 moves the pin 256 toward the right-hand end of the cam-slot 242 in the lever 238 and raises the abutment 246 of the lever upwardly out of register with the surface 359 on the coin-responsive element 348. By the time the fourth notch 295 of the notched portion 294 of the cam has moved under the sharp end 269 of latch 270—and this occurs before the slide 174 has moved its coin-receiving opening 192 into register with the coin reservoir 214—the abutment 246 on the lever 238 has been moved out of register with the surface 359 on the coin-responsive element 358. The fourth notch 295 of the notched portion 294 makes sure that the de-energization of the motor 90 will not give a patron an extra nickel.

Continued counter clockwise rotation of the shaft 94 enables the pin 182 on the slide 174 to rotate the latch 326 far enough to rotate the coin-responsive element 348 to its full counter clockwise position. In that position, the surface 359 on that coin-responsive element has moved to the left of the abutment 246 on the lever 238, and the coin-holding surface 358 has moved out of engagement with the quarter; and thereupon the quarter falls downwardly to the accepted coin chute 42.

Continued counter clockwise rotation of the shaft 94 moves the rise 312 beyond the roller 188 on slide 174, and also moves the high dwell 284 out of engagement with the roller 265 on the lower arm of lever 252. The movement of the rise 312 beyond the roller 188 permits the slide 174 to move to the left and thereby permits the latch 326 to move to slide-latching position, because a coin no longer holds the coin-responsive element 348 against rotation to its clockwise position. The movement of the high dwell 284 out of engagement with the roller 265 enables the spring 266 to rotate the lever 252 in the counter clockwise direction and force the lever 222 to rotate upwardly to its normal raised position while permitting the lever 238 to rotate downwardly to its normal lower position. At such time, the components of the change-making device are again in the position shown by FIG. 1. During the quarter operation, a pulse was sent to the vending machine and four nickels were paid out by the slide 174. Each of the rises 322, 306, 308 and 310 led to the paying out of a nickel, but the rise 312 did not; the quarter falling to the accepted coin chute before the rise 312 released the slide 174.

The four notches 295 of the notched section 294 of the cam are spaced apart from each other and are spaced circumferentially from the rises 322, 306, 308, 310 and 312. Those notches are so spaced and so positioned that they will prevent clockwise rotation of the cam and left-hand movement of the slide 174 to coin-freeing position between the time the slide has moved close enough to the reservoir 214 to permit a nickel to pass from that reservoir into the coin-receiving opening 192 of that slide and the time the next succeeding rise of the cam moves out of engagement with the roller 188. In this way, the paying out of extra nickels is prevented even if the power to the motor is shut off during a cycle of operation.

Ten Cent Sales Price

Where it is desired to use the change-making device of the present invention in a vending machine that vends products for ten cents, the two screws 300 are loosened and the front section 320 of the cam is moved outwardly to free the left-hand openings 325 thereof from the pin 293 on the notched portion 294 of that cam. Thereafter, the front portion 320 is rotated in the clockwise direction until the other opening 325 is in register with the pin 293; and at that time the rise 322 is adjacent the rise 306 on the four-lobe section 304 of the cam. The screws 300 can then be passed through the openings, not shown, in the front portion 320 of the cam and seated in the other pair of openings 318 in the four-lobe section 304 of the cam. Where this is done, the rise 314, rather than the rise

322, will be engaging the roller 188 on the slide 174 in the normal position of the change-making device. Also, a slug rejector will be used that diverts every other nickel direct to the coin reservoir 214 so it by-passes the switch arm 110.

If a dime is inserted, it will send an impulse to the vending machine by moving the coin switch 110 downwardly and it will start the motor 90 by moving the switch actuator 102 downwardly toward the magnet 230 on the lever 222. The energization of the motor 90 will cause the shaft 94 to pass through a complete cycle, but no nickels will be paid out because the rise 314 will not move the slide 174 far enough to the right to rotate the latch 326 to slide-freeing position; and therefore when the roller 188 is freed by the rise 314, the pin 182 will be caught and held by the notch 328. The rise 306 will move the slide 174 far enough to the right to rotate the coin-responsive element 364 to coin-freeing position and cause it to free the dime.

If desired, of course, the coin-responsive element 364 could be removed; and that portion of the switch wire 102 which extends into the dime passageway could be cut off. In such a case the motor 90 would not even operate when a dime was inserted.

If a quarter is inserted, the quarter will supply an impulse to the vending machine by moving the switch wire 110 downwardly, and it will start the motor 90 by moving the switch wire 102 downwardly adjacent the magnet 230. The motor 90 will cause the output shaft 94 to make one complete revolution; and during that revolution, the rises 314, 306, 308, 310 and 312 will successively engage and move the roller 188. However, the rise 314 has such a short outer radial dimension that it can not move the slide 174 far enough to move the latch 326 to slide-freeing position. Consequently, only three nickels will be paid out during the revolution of the shaft 94; and those nickels will be paid out as the slide is released by the rises 306, 308 and 310. The coin-responsive element 348 is made so its coin-feeling portion is normally closer to the flange 38 of frame 30 than is the coin-feeling portion of the corresponding coin-responsive element of the said co-pending application; and this is important in keeping the quarter from moving down into coin-feeling position when the rise 314 causes the slide to rotate the latch 326.

If two nickels are inserted, the first nickel will be diverted away from the switch arm 110 by the slug rejector. The second nickel will, however, engage the switch wire 110 and cause the switch 106 to send an impulse to the vending machine. In this simple and easy way, the change-making device of the present invention can be set for use with vending machines selling products for five cents or ten cents.

Whereas the drawing and accompanying description have shown and described a preferred embodiment of the present invention it should be apparent to those skilled in the art that various changes may be made in the form of the invention without affecting the scope thereof.

What we claim is:

1. A coin-operated device that has a coin passageway, a second coin passageway, a coin-responsive element movable relative to the first said coin passageway, a second coin-responsive element movable relative to said second coin passageway, each of said coin-responsive elements having a coin-holding portion that is movable to coin-freeing position to hold a coin and that is movable to coin-freeing position to free said coin, an element to move said coin-responsive elements toward coin-freeing position, a cam, an output shaft on which said cam is mounted, a motor that rotates said output shaft through one complete revolution during each cycle of said coin-operated device, an electric switch with contacts that are selectively movable to motor-energizing position or to motor de-energizing position, an actuator for said switch that is biased to motor de-energizing position to enable said contacts of said switch to be in motor de-energizing

position but is movable to motor-energizing position to enable said contacts to be in motor-energizing position, said switch actuator being engageable by coins in said coin passageways and being movable by said coins toward motor-energizing position, a movable element, a linkage intermediate said movable element and said cam on said output shaft that normally holds said movable element in motor de-energizing position but that responds to rotation of said cam and said output shaft to free said movable element for movement to motor-energizing position, said movable element having portions thereof that are spaced apart to permit said switch actuator, when said movable element is in motor de-energizing position, to move from motor de-energizing position to motor-energizing position, one of said portions holding, when said movable element is in motor de-energizing position, said switch actuator in motor-energizing position after said switch actuator has been moved to motor-energizing position by a coin in one of said passageways, said movable element responding to rotation of said cam and said output shaft to move to motor-energizing position, the other of said portions holding said switch actuator in motor-energizing position when said movable element is in motor-energizing position, said linkage, at the end of the cycle of said coin-operated device, causing said movable element to move to motor de-energizing position, thereby permitting said switch actuator to return to motor de-energizing position, a plurality of abutments on said cam, a latch mounted adjacent said cam and in register with said abutments on said cam, said latch coacting with said abutments to limit reverse rotation of said cam and said output shaft, a gauging element that is movable to provide two individually different predetermined limits to the movement of said coin-responsive elements, and a second linkage that is intermediate said gauging element and said cam on said output shaft and that responds to rotation of said cam and said output shaft to move said gauging element.

2. A coin-operated device that has a coin passageway, a second coin passageway, a pivot adjacent said coin passageway, a coin-responsive element mounted on said pivot for rotation relative to the first said coin passageway, said coin-responsive element being rotatable to coin-holding and coin-freeing positions, a second coin-responsive element mounted on said pivot for rotation relative to said second coin passageway, said second coin-responsive element being rotatable to coin-holding and coin-freeing positions, said coin-responsive elements rotating about said pivot as a unit, a coin reservoir, a coin ejector that has a coin-receiving opening therein, a cam that can rotate to move said ejector in one direction to place said coin-receiving opening of said ejector in register with the outlet of said coin reservoir and that can continue to rotate to free said ejector for movement in the opposite direction to coin-freeing position, a second pivot adjacent said ejector, a latch that is mounted on said second pivot for rotation relative to said ejector, said ejector engaging and rotating said latch as said ejector approaches the end of its path of movement in said one direction, a lost-motion connection between said coin-responsive elements and said latch, a third pivot, a gauging lever that is rotatably mounted on said third pivot and that has a plurality of abutments thereon, a stop that normally holds said gauging lever in an initial position, the first said coin-responsive element having a surface thereon that is in register with one of said abutments on said gauging lever whenever said gauging lever is in said initial position, said surface on said first said coin-responsive element being in register with another of said abutments on said gauging lever whenever said gauging lever is in an intermediate position, said surface on said first said coin-responsive element being out of register with said abutments on said gauging lever whenever said gauging lever is in fully moved position, a fourth pivot, and a second lever that is mounted on said fourth pivot and that is movable by said cam to move said gauging

lever, said first said coin-responsive element and the said coin passageway therefor accommodating coins that require a predetermined number of coins to be paid out from said coin-reservoir by said ejector, said second coin-responsive element and the other of said coin passageways accommodating coins that require a lesser predetermined number of coins to be paid out from said coin reservoir by said ejector, said second lever normally permitting said gauging lever to rest against said stop but responding to rotation of said cam to successively move said gauging lever to its intermediate position and to its fully moved position before permitting said gauging lever to return to said initial position, said second coin-responsive element being in coin-holding position whenever said surface on said first said coin-responsive element is adjacent said one abutment on said gauging lever and being in coin-freeing position whenever said surface on said first said coin-responsive element is adjacent said other abutment on said gauging lever, said cam moving said second lever to move said gauging lever to its intermediate position and moving said ejector toward the end of its path of movement in said one direction to rotate said latch and thereby rotate said surface on said first said coin-responsive element adjacent said other abutment on said gauging lever after the last of said lesser predetermined number of coins has been paid out from said coin reservoir by said ejector, said cam moving said second lever to move said gauging lever to its fully moved position and moving said ejector all the way to the end of its path of movement in said one direction to rotate said latch and thereby rotate said surface on said first said coin-responsive element past said other abutment on said gauging lever after the last of the first said predetermined number of coins has been paid out from said coin reservoir by said ejector, said abutments being adapted to limit rotation of said coin-responsive elements in response to ejector-induced rotation of said latch, said lost-motion connection between said coin-responsive elements and said latch permitting overtravel of said latch and ejector after rotation of said coin-responsive elements has been stopped by said one or said other abutments on said gauging lever.

3. A coin-operated device that has a coin passageway, a second coin passageway, a coin responsive element mounted for movement relative to the first said coin passageway, a second coin-responsive element mounted for movement relative to said second coin passageway, a coin reservoir, a coin ejector that has a coin-receiving opening therein, said coin-responsive elements being movable to coin-holding and coin-freeing positions, a cam that can move said ejector in one direction to place said coin-receiving opening in register with the outlet of said coin reservoir and that can continue to move to free said ejector for movement in the opposite direction to coin-freeing position, a latch that is mounted adjacent said ejector and that is movable by said ejector, said ejector engaging and moving said latch as said ejector approaches the end of its path of movement in said one direction, a lost-motion connection between said coin-responsive elements and said latch, a gauging lever that is movably mounted adjacent the first said coin-responsive element and that has a plurality of abutments thereon, said first said coin-responsive element having a surface thereon that is in register with one of said abutments on said gauging lever whenever said gauging lever is in its initial position, said surface on said first said coin-responsive element being in register with another of said abutments on said gauging lever whenever said gauging lever is in an intermediate position, said surface on said first said coin-responsive element being out of register with said abutments on said gauging lever whenever said gauging lever is in fully moved position, and a second lever that is movable by said cam to move said gauging lever, said first said coin-responsive element and the said coin passageway therefor accommodating coins that require a predetermined number of coins to be paid out from

said coin-reservoir by said ejector, said second coin-responsive element and the other of said coin passageways accommodating coins that require a lesser predetermined number of coins to be paid out from said coin reservoir by said ejector, said second lever normally permitting said gauging lever to rest in its initial position but responding to movement of said cam to successively move said gauging lever to its intermediate position and to its fully moved position before permitting said gauging lever to return to said initial position, said second coin-responsive element being in coin-holding position whenever said surface on said first said coin-responsive element is in register with and adjacent said one abutment on said gauging lever and being in coin-freeing position whenever said surface on said first said coin-responsive element is in register with an adjacent said other abutment on said gauging lever, said cam moving said second lever to move said gauging lever to its intermediate position and moving said ejector toward the end of its path of movement in said one direction to move said latch and thereby move said surface on said first said coin-responsive element adjacent said other abutment on said gauging lever after the last of said lesser predetermined number of coins has been paid out from coin reservoir by said ejector, said cam moving said second lever to move said gauging lever to its fully moved position and moving said ejector all the way to the end of its path of movement in said one direction to move said latch and thereby move said surface on said first said coin-responsive element past said other abutment on said gauging lever after the last of the first said predetermined number of coins has been paid out from said coin reservoir by said ejector, said abutments limiting movement of said coin-responsive elements in response to ejector-induced movement of said latch, said lost-motion connection between said coin-responsive elements and said latch permitting overtravel of said latch and ejector after movement of said coin-responsive elements has been stopped by said one or said other abutments on said gauging lever.

4. A coin-operated device that has a motor to drive an output shaft through one complete revolution during each cycle of said coin-operated device, an electric switch with contacts that are selectively movable to motor-energizing position or to motor de-energizing position, an actuator for said switch that is made of magnetic material and that is biased to motor de-energizing position to enable said contacts of said switch to be in motor de-energizing position but is movable to motor-energizing position to enable said contacts to be in motor-energizing position, a coin passageway that guides coins for movement adjacent said switch actuator to enable said coins to move said switch actuator to motor-energizing position, a pivot, a lever rotatably mounted on said pivot, a second pivot, a second lever rotatably mounted on said second pivot, and a cam on said output shaft that normally holds said second lever in position to hold the first said lever in an upper, motor de-energizing position but that rotates with said output shaft to permit said second lever to free the first said lever for movement to a lower, motor-energizing position, said first lever having an abutment and a magnet thereon that are oppositely disposed of said switch actuator, said abutment being disposed above the level of said magnet, said abutment and said magnet being spaced apart to permit said switch actuator, when said first lever is in its upper, motor de-energizing position, to move from motor de-energizing position to motor-energizing position, said magnet holding, when said first lever is in its upper, motor-de-energizing position, said switch actuator in motor-energizing position after said switch actuator has been moved to motor-energizing position by a coin in said passageway, said first lever responding to freeing movement of said second lever to move downwardly to said lower, motor-energizing position, said abutment on said first lever overlying said switch actuator and holding said switch actuator in motor-energizing posi-

tion when said first lever is in said lower, motor-energizing position, said cam returning said second lever to its normal position at the end of the cycle of said coin-operated device and causing said second lever to move said first lever to its upper, motor de-energizing position, thereby permitting said switch actuator to return to motor de-energizing position.

5. A coin-operated device that has a motor to drive an output shaft through one complete revolution during each cycle of said coin-operated device, an electric switch with contacts that are selectively movable to motor-energizing position or to motor de-energizing position, an actuator for said switch that is made of magnetic material and that is biased to motor de-energizing position to enable said contacts of said switch to be in motor de-energizing position but is movable to motor-energizing position to enable said contacts to be in motor-energizing position, a coin passageway that guides coins for movement adjacent said switch actuator to enable said coins to move said switch actuator to motor-energizing position, a pivot, a lever rotatably mounted on said pivot, a second pivot, a second lever rotatably mounted on said second pivot, and a cam on said output shaft that normal holds said second lever in position to hold the first said lever in motor de-energizing position but that rotates with said output shaft to permit said second lever to free the first said lever for movement to motor-energizing position, said first lever having an abutment and a magnet thereon that are oppositely disposed of said switch actuator, said abutment and said magnet being spaced apart to permit said switch actuator, when said first lever is in its motor de-energizing position, to move from motor de-energizing position to motor-energizing position, said magnet holding, when said first lever is in its motor de-energizing position, said switch actuator in motor-energizing position after said switch actuator has been moved to motor-energizing position by a coin in said passageway, said first lever responding to freeing movement of said second lever to move to said motor-energizing position, said abutment on said first lever holding said switch actuator in motor-energizing position when said first lever is in said motor-energizing position, said cam returning said second lever to its normal position at the end of the cycle of said coin-operated device and causing said second lever to move said first lever to its motor de-energizing position, thereby permitting said switch actuator to return to motor de-energizing position.

6. A coin-operated device that has a motor to drive an output shaft through one complete revolution during each cycle of said coin-operated device, an electric switch with contacts that are selectively movable to motor-energizing position or to motor de-energizing position, an actuator for said switch that is made of magnetic material and that is biased to motor de-energizing position to enable said contacts of said switch to be in motor de-energizing position but is movable to motor-energizing position to enable said contacts to be in motor-energizing position, a coin passageway that guides coins for movement adjacent said switch actuator to enable said coins to move said switch actuator to motor-energizing position, a pivot, a lever rotatably mounted on said pivot, and a linkage intermediate said lever and said output shaft that normally holds said lever in motor de-energizing position but that responds to rotation of said output shaft to permit said lever to move to motor-energizing position, said lever having an abutment and a magnet thereon that are oppositely disposed of said switch actuator, said abutment and said magnet being spaced apart to permit said switch actuator, when said lever is in motor de-energizing position, to move from motor de-energizing position to motor-energizing position, said magnet holding, when said lever is in motor de-energizing position, said switch actuator in motor-energizing position after said switch actuator has been moved to motor-energizing position by a coin in said passageway, said lever responding to rotation of said output shaft to move to motor-energizing position,

said abutment on said lever holding said switch actuator in motor-energizing position when said lever is in motor-energizing position, said linkage, at the end of the cycle of said coin-operated device, causing said lever to move to motor de-energizing position, thereby permitting said switch actuator to return to motor de-energizing position.

7. A coin-operated device that has a motor to drive a shaft through one complete revolution during each cycle of said coin-operated device, an electric switch with contacts that are selectively movable to motor-energizing position or to motor de-energizing position, an actuator for said switch that is biased to motor de-energizing position to enable said contacts of said switch to be in motor de-energizing position but is movable to motor-energizing position to enable said contacts to be in motor-energizing position, a coin passageway that guides coins for movement adjacent said switch actuator to enable said coins to move said switch actuator to motor-energizing position, a movable element, and a linkage intermediate said movable element and said output shaft that normally holds said movable element in motor de-energizing position but that responds to rotation of said output shaft to free said movable element for movement to motor-energizing position, said movable element having portions thereof that are spaced apart to permit said switch actuator, when said movable element is in motor de-energizing position, to move from motor de-energizing position to motor-energizing position, one of said portions being a magnet and holding, when said movable element is in motor de-energizing position, said switch actuator in motor-energizing position after said switch actuator has been moved to motor-energizing position by a coin in said passageway, said movable element responding to rotation of said shaft to move to motor-energizing position, the other of said portions holding said switch actuator in motor-energizing position when said movable element is in motor-energizing position, said linkage, at the end of the cycle of said coin-operated device, causing said movable element to move to motor de-energizing position, thereby permitting said switch actuator to return to motor de-energizing position.

8. A coin-operated device that has a cycle of operation, an electric switch that is actuatable to start said cycle of operation of said device, an actuator for said switch that is movable to switch-actuating position to actuate said switch and thereby cause said switch to start said cycle of operation of said device, said switch actuator being movable to switch-actuating position by coins inserted in said device, an electromotive element that is energized by the closing of said switch, and a movable element that is normally in one position but is movable to a second position as a result of the energization of said electromotive element, said movable element holding said switch actuator in switch-actuating position whenever said movable member is in said second position and freeing said switch actuator from switch-actuating position whenever said movable element is moved back to said one position as a result of continued energization of said electromotive element, said movable element having a magnet to attract and hold said switch actuator in switch-actuating position when said movable element is in said one position and said switch actuator has been moved to switch-actuating position by a coin, said movable element having an abutment to hold said switch actuator in switch actuating position when said movable element is in its second position, said magnet and said abutment being oppositely disposed of said switch actuator, said movable element being movable back to said one position at the end of said cycle of operation of said device.

9. A coin-operated device that has a cycle of operation, an electric switch that is actuatable to start said cycle of operation of said device, an actuator for said switch that is movable to switch-actuating position to actuate said switch and thereby cause said switch to

start said cycle of operation of said device, said switch actuator being movable to switch-actuating position by coins inserted in said device, an electromotive element that is energized by the closing of said switch, and a movable element that is normally in one position but is movable to a second position as a result of the energization of said electromotive element, said movable element having a magnet that is in register with said switch actuator and having an abutment that is in register with said switch actuator, said magnet underlying said switch actuator and said abutment overlying said switch actuator, said magnet being spaced from said abutment to permit said switch actuator to move relative to said magnet and said abutment, said magnet being adapted, when said movable element is in said one position and said switch actuator has been moved to switch-actuating position by a coin, to hold said switch actuator in switch-actuating position, said abutment being adapted, when said movable element is in said second position, to hold said switch actuator in switch-actuating position, said magnet moving away from said switch actuator and freeing said switch actuator as said movable element moves to said second position, said abutment intercepting the freed switch actuator and holding said switch actuator in switch-actuating position as said movable member moves to said second position, said movable element being movable back to said one position as a result of continued energization of said electromotive element at the end of said cycle of operation of said device.

10. A coin-operated device that has a cycle of operation, an electric switch that is actuatable to start said cycle of operation of said device, an actuator for said switch that is movable to switch-actuating position to actuate said switch and thereby cause said switch to start said cycle of operation of said device, said switch actuator being movable to switch-actuating position by coins inserted in said device, and electromotive element that is energized by the closing of said switch, and a movable element that is normally in one position but is movable to a second position as a result of the energization of said electromotive element, said movable element having a magnet and an abutment, said magnet being adapted, when said movable element is in said one position, to respond to switch-actuating movement of said switch actuator to hold said switch actuator in switch-actuating position, said abutment holding said switch actuator in switch-actuating position whenever said movable element is in said second position and freeing said switch actuator from switch-actuating position whenever said movable element is moved back to said one position, said movable element being movable back to said one position as a result of continued energization of said electromotive element at the end of said cycle of operation of said device, whereby said movable element can coact with said switch actuator to hold said switch actuated throughout the entire cycle of operation of said device.

11. A coin-operated device that has a coin passageway, a second coin passageway, a pivot adjacent said coin passageways, a coin-responsive element that is at least partially disposed within the first said coin passageway and that is mounted on said pivot for rotation relative to the first said coin passageway, said coin-responsive element being rotatable to coin-holding and coin-freeing positions, a second coin-responsive element that is at least partially disposed within said second coin passageway and that is mounted on said pivot for rotation relative to said second coin passageway, said second coin-responsive element being rotatable to coin-holding and coin-freeing positions, a pin holding said coin-responsive elements for rotation as a unit about said pivot, a coin reservoir, a coin ejector that is adjacent said coin reservoir and that has a coin-receiving opening 75 therein, a multi-lobe cam that can rotate to move said

ejector in one direction to place said coin-receiving opening of said ejector in register with the outlet of said coin reservoir so coins can pass from said coin reservoir to said coin-receiving opening and that can continue to rotate to free said ejector for movement in the opposite direction to coin-freeing position, a second pivot adjacent said ejector, a latch that has a camming surface thereon and that is mounted on said second pivot for rotation relative to said ejector, a second pin that is mounted on said latch, said ejector engaging said camming surface on said latch and rotating said latch as said ejector approaches the end of its path of movement in said one direction, a connecting rod that interconnects said latch and said coin-responsive elements, a slot in said connecting rod that accommodates said second pin, said slot and said second pin providing a lost-motion connection between said connecting rod and said latch, a spring extending between said second pin and said connecting rod to hold said second pin adjacent one end of said slot, a third pivot, a gauging lever that is rotatably mounted on said third pivot and that has a plurality of abutments thereon, a stop that normally holds said gauging lever in an initial position, the first said coin-responsive element having a surface thereon that is in register with one of said abutments on said gauging lever whenever said gauging lever is in said initial position, said surface on said first said coin-responsive element being in register with another of said abutments on said gauging lever whenever said gauging lever is in an intermediate raised position, said surface on said first said coin-responsive element being out of register with said abutments on said gauging lever whenever said gauging lever is in fully raised position, a fourth pivot, and a second lever that is mounted on said fourth pivot and that is movable by said cam to raise said gauging lever, said first said coin-responsive element and the said coin passageway therefor accommodating coins that require a predetermined number of coins to be paid out from said coin-reservoir by said ejector, said second coin-responsive element and the other of said coin passageways accomodating coins that require a lesser predetermined number of coins to be paid out from said coin reservoir by said ejector, said second lever normally permitting said gauging lever to rest against said stop and thereby be in said initial position but responding to rotation of said cam to successively move said gauging lever to its intermediate raised position and to its fully raised position before permitting said gauging lever to return to said initial position, said second coin-responsive element being in coin-holding position whenever said surface on said first said coin-responsive element is in register with and adjacent said one abutment on said gauging lever and being in coin-freeing position whenever said surface on said first said coin-responsive element is in register with and adjacent said other abutment on said gauging lever, said cam moving said second lever to move said gauging lever to its intermediate raised position and one of said lobes of said cam moving said ejector toward the end of its path of movement in said one direction to rotate said latch and thereby rotate said surface on said first said coin-responsive element adjacent said other abutment on said gauging lever after the last of said lesser predetermined number of coins has been paid out from said coin reservoir by said ejector, said cam moving said second lever to move said gauging lever to its fully raised position and another of said lobes of said cam moving said ejector all the way to the end of its path of movement in said one direction to rotate said latch and thereby rotate said surface on said first said coin-responsive element below said other abutment on said gauging lever after the last of the first said predetermined number of coins has been paid out from said coin reservoir by said ejector, said abutments being adapted to limit rotation of said coin-responsive elements toward coin-freeing position in response to ejector-in-

duced rotation of said latch, said lost-motion connection between said connecting rod and said latch permitting said second pin to move toward the opposite end of said slot to permit overtravel of said latch and ejector after rotation of said coin-responsive elements has been stopped by said one or said other abutments on said gauging lever, said one lobe of said multilobe cam being the first lobe to move said ejector in said one direction during a cycle of operation of said coin-operated device, said other lobe of said cam being the last lobe to move said ejector in said one direction during said cycle of operation, said other lobe having a rise with a greater outer radial dimension than the outer radial dimension of said one lobe.

12. A coin-operated device that has a coin passageway, a second coin passageway, a coin-responsive element mounted for movement relative to the first said coin passageway, a second coin-responsive element mounted for movement relative to said second coin passageway, the first said coin-responsive element being movable into and out of coin-holding position and into and out of coin-freeing position, said second coin-responsive element being movable into and out of coin-holding position and into and out of coin-freeing position, a coin reservoir, a coin ejector that has a coin-receiving opening therein, an electric motor, a cam that is driven by said motor and that can move said ejector relative to said coin reservoir, said ejector being movable in one direction to place said coin-receiving opening thereof in register with the outlet of said coin reservoir and being movable in the opposite direction to coin-freeing position, a latch that is mounted adjacent said ejector and that selectively holds said ejector with its coin-receiving opening adjacent said outlet of said coin reservoir or frees said ejector for movement to coin-freeing position, a connection between said latch and said coin-responsive elements that holds said latch in ejector-freeing position whenever said first said coin-responsive element feels a coin in said first said coin passageway and whenever said second coin-responsive element feels a coin in said second coin passageway and whenever said first said or said second coin-responsive element is in its coin-freeing position, a gauging lever adjacent said first said coin-responsive element, and a linkage between said motor and said gauging lever that moves said gauging lever relative to said first said coin-responsive element, said motor moving said coin-responsive elements toward their coin-freeing positions but permitting said coin-responsive elements to stop short of said coin-freeing positions and thereafter permitting said coin-responsive elements to move away from said coin-freeing positions and to feel for and press against coins in said coin passageways, said gauging lever acting whenever it is in its initial position to permit said motor to move said first said coin-responsive element far enough toward its coin-freeing position to enable a coin in the first said coin passageway to move into position to be felt by said first said coin-responsive element but positively blocking movement of said first said coin-responsive element to its coin-freeing position, said gauging lever being movable by said motor and linkage to a second position, after said first said coin-responsive element has felt for a coin, to permit movement of said first said coin-responsive element closer to its coin-freeing position to move said second coin-responsive element to its coin-freeing position but positively preventing movement of said first said coin-responsive element to its coin-freeing position, whereby said gauging lever can prevent premature releasing of coins by said first said coin-responsive element while permitting said second coin-responsive element to release coins.

13. A coin-operated device that has a coin passageway, a second coin passageway, a coin-responsive element movable relative to the first said coin passageway, a second coin-responsive element movable relative to said sec-

ond coin passageway, said coin-responsive elements being movable into and out of coin-holding and coin-freeing positions, a coin reservoir, a coin ejector that has a coin-receiving opening therein, an electric motor for driving said ejector, said ejector being movable in one direction to place said coin-receiving opening thereof in register with the outlet of said coin reservoir and being movable in the opposite direction to coin-freeing position, an actuating element movably mounted adjacent said ejector, said ejector moving said actuating element as said ejector approaches the end of its path of movement in said one direction, said actuating element responding to ejector-induced movement to move said coin-responsive elements, a gauging lever that has a plurality of abutments thereon, and a linkage between said motor and said gauging lever that moves said gauging lever relative to the first said coin-responsive element, said first said coin-responsive element having a surface thereon that is in register with one of said abutments on said gauging lever whenever said gauging lever is in its initial position and that coacts with said one abutment to permit said first said coin-responsive element to be moved far enough toward its coin-freeing position by ejector-induced movement of said actuating element to enable a coin in the first said coin passageway to move into position where it can be felt by said first said coin-responsive element but to positively prevent movement of said first said coin-responsive element to its coin-freeing position, said actuating element subsequently permitting said first said coin-responsive element to feel for and press against said coin in said first said coin passageway, said surface on said first said coin-responsive element being in register with another of said abutments on said gauging lever whenever said gauging lever is in an intermediate position and coacting with said other abutment to permit said second coin-responsive element to be moved far enough toward its coin-freeing position by ejector-induced movement of said actuating element to free a coin held in said second passageway by said second coin-responsive element but to positively prevent movement of said first said coin-responsive element to its coin-freeing position, said first said coin-responsive element subsequently being freed by said actuating element to press against and feel for a coin in said first said coin passageway, said surface on said first said coin-responsive element being out of register with said abutments on said gauging lever whenever said gauging lever is in fully moved position so said first said coin-responsive element can respond to ejector-induced movement of said actuating element to move to its coin-freeing position and thereby free a coin held in said first said coin passageway by said first said coin-responsive element, said first said coin-responsive element and said first said coin passageway accommodating coins that require a predetermined number of coins to be paid out from said coin reservoir by said ejector, said second coin-responsive element and said second coin passageway accommodating coins that require a lesser predetermined number of coins to be paid out from said coin reservoir by said ejector, said motor and linkage successively moving said gauging lever to its intermediate position and to its fully moved position before said gauging lever returns to its initial position, said second coin-responsive element being in coin-holding position whenever said surface on said first said coin-responsive element is adjacent said one abutment on said gauging lever and being in coin-freeing position whenever said surface on said first said coin-responsive element is adjacent said other abutment on said gauging lever, said gauging lever being in intermediate position and said surface on said first said coin-responsive element being adjacent said other abutment on said gauging lever after the last of said lesser predetermined number of coins has been paid out from said coin reservoir by said ejector, said gauging lever being in fully moved position and said surface on said first said coin-responsive element being out of register with said other abutment on said gauging

lever after the last of the first said predetermined number of coins has been paid out from said coin reservoir by said ejector.

14. A coin-operated device that has a coin passageway, 5 a coin-responsive element movable relative to said coin passageway, said coin-responsive element being movable to coin-holding and coin-freeing positions, a coin reservoir, a coin ejector that has a coin-receiving opening therein, an electric motor for driving said ejector, said 10 ejector being movable in one direction to place said coin-receiving opening thereof in register with the outlet of said coin reservoir and being movable in the opposite direction to coin-freeing position, an actuating element movably mounted adjacent said ejector, said ejector engaging and moving said actuating element as said ejector approaches the end of its path of movement in said one direction, said actuating element responding to ejector-induced movement to move said coin-responsive element, a gauging lever that has an abutment thereon and that 15 has an initial position and a fully moved position, and a linkage between said motor and said gauging lever that moves said gauging lever between its initial and fully moved positions and that moves said gauging lever relative to said coin-responsive element, said coin-responsive element having a surface thereon that is in register with said abutment on said gauging lever whenever said gauging lever is in its initial position and that coacts with said abutment to permit said coin-responsive element to move far enough toward its coin-freeing position to permit a 20 coin in said coin passageway to move into position to be felt by said coin-responsive element but to positively keep said coin-responsive element from moving to its coin-freeing position, said surface on said coin-responsive element being out of register with said abutment whenever said 25 gauging lever is in its fully moved position to permit movement of said coin-responsive element to its coin-freeing position, said motor and linkage moving said gauging lever to its fully moved position after said coin-responsive element has felt for a coin in said coin passageway, said 30 coin-responsive element and said coin passageway accommodating coins that require a predetermined number of coins to be paid out from said coin reservoir by said ejector, said coin-responsive element being in coin-holding position whenever said surface thereon is adjacent said 35 abutment on said gauging lever and being in coin-freeing position whenever said surface thereon has moved past said abutment on said gauging lever, said motor and linkage permitting said coin-responsive element to feel for a coin in said coin passageway until the last of said predetermined number of coins has been paid out from said 40 coin reservoir by said ejector and thereafter moving said gauging lever to its fully moved position to permit said coin-responsive element to be moved to its coin-freeing position.

15. A coin-operated device that has a coin passageway, 45 a second coin passageway, a coin-responsive element mounted for movement relative to the first said coin passageway, a second coin-responsive element mounted for movement relative to said second coin passageway, a coin 50 reservoir, a coin ejector that has a coin-receiving opening therein, an electric motor, a cam that is driven by said motor and that can move said ejector relative to said coin reservoir, said ejector being movable in one direction to place said coin-receiving opening thereof in register with the outlet of said coin reservoir and being movable in the opposite direction to coin-freeing position, a latch that is mounted adjacent said ejector and that 55 selectively holds said ejector with its coin-receiving opening adjacent said outlet of said coin reservoir or frees said ejector for movement to coin-freeing position, a connection between said latch and said coin-responsive elements, a gauging lever adjacent one of said coin-responsive elements, and a linkage between said motor and said gauging lever that moves said gauging lever relative to said first said coin-responsive element, said gauging lever 60

75

having a plurality of abutments thereon that are selectively registerable with a surface on said first said coin-responsive element, said gauging lever initially having one of said abutments thereon in register with said surface on said first said coin-responsive element and coacting with said surface on said first said coin-responsive element to permit movement of said coin-responsive elements far enough toward their coin-freeing positions to permit coins in said coin passageways to move into position to be felt by said coin-responsive elements but to positively prevent movement of said coin-responsive elements to their coin-freeing positions, said coin-responsive elements subsequently being permitted to feel for and press against coins in said coin passageways, said gauging lever being movable to a second position to dispose another of said abutments thereon in register with said surface on said first said coin-responsive element and coacting with said surface on said first said coin-responsive element to permit movement of said second coin-responsive element to its coin-freeing position while positively preventing movement of said first said coin-responsive element to its coin-freeing position, whereby a coin held in said second coin passageway by said second coin-responsive element can be freed but a coin held in said first said coin passageway by said first said coin-responsive element will continue to be held by said first said coin-responsive element, said gauging lever being moved to said second position after said second coin-responsive element has felt for a coin in said second coin passageway.

16. A coin-operated device that has a coin passageway, a second coin passageway, a coin-responsive element movable relative to the first said coin passageway, a second coin-responsive element movable relative to said second coin passageway, each of said coin-responsive elements having a coin-holding portion that is movable to coin-holding position to hold a coin and that is movable to coin-freeing position to free said coin, an electric motor, an actuating element that responds to said motor to move said coin-responsive elements far enough toward their coin-freeing positions to enable coins in said coin passageways to move into position to be felt by said coin-responsive elements and that subsequently permits said coin-responsive elements to feel for and press against said coins, a gauging element, and a linkage between said motor and said gauging element that permits said gauging element to remain in its initial position for a predetermined length of time and that subsequently causes said gauging element to move to a second position, said gauging element acting whenever it is in its initial position to permit said actuating element to respond to said motor to move said coin-responsive elements far enough toward their coin-freeing positions to enable coins in said coin passageways to move into position to be felt by said coin-responsive elements but to positively keep said coin-responsive elements from moving to their coin-freeing positions, said gauging element acting whenever it is in its second position to permit said actuating member to respond to said motor to move said coin-responsive elements far enough toward their coin-freeing positions to enable said second coin-responsive element to free a coin held by it in said second coin passageways but not far enough to enable said first said coin-responsive element to free a coin held by it in said first coin passageway.

17. A coin-operated device that has a coin passageway, a second coin passageway, a coin-responsive element movable relative to the first said coin passageway, a second coin-responsive element movable relative to said second coin passageway, each of said coin-responsive elements having a coin-holding portion that is movable to coin-holding position to hold a coin and that is movable to coin-freeing position to free said coin, an electric motor, an actuating element that responds to said motor to move said coin-responsive elements far enough toward their coin-freeing positions to enable coins in said coin passageways to move into position to be felt by said coin-

responsive elements and that subsequently permits said coin-responsive elements to feel for and press against said coins, a gauging element that has a plurality of abutments thereon, and a linkage between said motor and said gauging element that permits said gauging element to remain in its initial position for a predetermined length of time and that subsequently causes said gauging element to move to a second position and that finally causes said gauging element to move to a third position, one of said abutments on said gauging element acting whenever said gauging element is in its initial position to permit said actuating element to respond to said motor to move said coin-responsive elements far enough toward their coin-freeing positions to enable coins in said coin passageways to move into position to be felt by said coin-responsive elements but to positively keep said coin-responsive elements from moving to their coin-freeing positions, another of said abutments on said gauging element acting whenever said gauging element is in its second position to permit said actuating member to respond to said motor to move said coin-responsive elements far enough toward their coin-freeing positions to enable said second coin-responsive element to free a coin held by it in said second coin passageway but not far enough to enable said first said coin-responsive element to free a coin held by it in said first coin passageway, said abutments being unable, whenever said gauging element is in its third position, to prevent movement of said coin-responsive elements to their coin-freeing positions.

18. A coin-operated device that has a coin passageway, a second coin passageway, a coin-responsive element movable relative to the first said coin passageway, a second coin-responsive element movable relative to said second coin passageway, a coin reservoir, a coin ejector that has a coin-receiving opening therein, said ejector being movable in one direction to place said coin-receiving opening thereof in register with the outlet of said coin reservoir and being movable in the opposite direction to coin-freeing position, a latch that is engageable with said ejector to prevent movement of said ejector, an electric motor, each of said coin-responsive elements having a coin-feeling portion that can feel a coin and that can be moved to coin-freeing position, said latch moving with said coin-responsive elements and being held out of engagement with said ejector whenever either of said coin-responsive elements feels a coin, a gauging element that is movable between an initial position and a second position, and a linkage between said motor and said gauging element to move said gauging element, said motor moving said coin-responsive elements toward their coin-freeing positions but thereafter permitting said coin-responsive elements to move toward and feel for coins in said coin passageways, said gauging element acting whenever it is in its initial position to permit said coin-responsive elements to be moved far enough toward their coin-freeing positions to permit coins in said coin passageways to move into position to be felt by said coin-responsive elements but to positively prevent movement of said coin-responsive elements to their coin-freeing positions, said motor and linkage subsequently causing said gauging element to move to a second position, said gauging element acting whenever it is in said second position to permit said coin-responsive elements to be moved far enough toward their coin-freeing positions to permit said second coin-responsive element to free a coin held by it in said second coin passageway but to positively keep said first said coin-responsive element from freeing a coin held by it in said first said coin passageway.

19. A coin-operated device that has a coin passageway, a pivot, a coin-responsive element mounted on said pivot for rotation relative to said coin passageway, said coin-responsive element being rotatable in one direction to a position where a coin can move intermediate said coin-responsive element and one wall of said coin passageway and be held for subsequent sensing of its presence and

being rotatable further in said direction to coin-freeing position, an electromotive element that causes movement of said coin-responsive element in said direction, said electromotive element initially moving said coin-responsive element to the first said position and then releasing said coin-responsive element to permit said coin-responsive element to move toward said one wall of said coin passageway to feel for and press against a coin in said coin passageway, said electromotive element subsequently moving said coin-responsive element through said first said position to said coin-freeing position to free a coin held in said coin passageway by said coin-responsive element, and a stop that is normally in an initial position but is movable to a second position, said stop acting whenever it is in its initial position to permit said electromotive element to move said coin-responsive element to the first said position but to keep said electromotive element from moving said coin-responsive element to said coin-freeing position, said electromotive element subsequently moving said stop to said second position, said stop acting whenever it is in said second position to permit said electromotive element to move said coin-responsive element to said coin-freeing position, whereby said stop permits freeing of coins but prevents premature freeing of said coins.

20. A coin-operated device that has a coin passageway, a pivot, a coin-responsive element that extends at least partially into said coin passageway and that is mounted on said pivot for rotation relative to said coin passageway, said coin-responsive element being rotatable to a position where a coin can move intermediate said coin-responsive element and one wall of said coin passageway and be held for subsequent sensing of its presence and being rotatable to coin-freeing position, an electromotive element that causes movement of said coin-responsive ele-

ment to the first said position and to said coin-freeing position, said electromotive element initially moving said coin-responsive element to the first said position and then releasing said coin-responsive element to permit said coin-responsive element to feel for and press against a coin in said coin passageway, said electromotive element subsequently moving said coin-responsive element to said coin-freeing position to free a coin held in said coin passageway by said coin-responsive element, and a stop that is normally in an initial position but is movable to a second position, said stop acting whenever it is in its initial position to permit said electromotive element to move said coin-responsive element to the first said position but to keep said electromotive element from moving said coin-responsive element to said coin-freeing position, said electromotive element subsequently moving said stop to said second position, said stop acting whenever it is in said second position to permit said electromotive element to move said coin-responsive element to said coin-freeing position.
